UNITED STATES PATENT OFFICE.

WILLIAM L. DODGE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 22, 1920. Serial No. 432,425.

To all whom it may concern:

Be it known that I, WILLIAM L. DODGE, a citizen of the United States, residing at Maplewood, in the county of Essex, State of New Jersey, have invented certain new and useful Improvements in Telephone Systems, of which the following is a full, clear, concise, and exact description.

This invention relates to improvements in switching systems wherein means are provided for controlling the transmission of current impulses for a plurality of trunk lines extending between widely separated offices, and has particular reference to such means as applied to telephone systems.

In systems of this character, it has been proposed to employ, at opposite ends of the common path, sending means for transmitting thereover codes of current impulses characteristic of the individual trunks and determined by the trunk line which is temporarily associated with the path for signaling purposes.

It is often desirable to extend a connection from an originating office to some distant office through an intermediate or tandem office by means of a sectionalized trunk line, the sections of which are connected at the intermediate office.

An object of this invention is to provide a system of this nature wherein the originating operator at one office may not only selectively and automatically extend a connection to terminate at a second office, but may also selectively and automatically extend such connection through the second office to terminate at a third office. In either case the selecting and operating current impulses are transmitted between adjacent offices over a common signaling path for the trunk lines interconnecting such offices.

It is also an object of the invention to provide means controlled over the common signaling path whereby an idle one of a plurality of trunks leading from the intermediate to any one of a plurality of terminating offices may be automatically selected and connected to the selected trunk leading from the originating office.

It is also an object to provide such a system wherein the originating operator maintains complete control of a connection extending through an intermediate office and the originating and terminating operators receive all supervisory signals occurring

while the through connections remains established.

Another object of the invention is to provide means whereby, when a connection requiring the use of an amplifier is selected, a properly balanced repeater set is rendered effective and associated with the talking circuit of the through connection in response to the selecting impulses transmitted over the common signaling path from the originating office.

In order to attain these objects, in accordance with one feature of the invention, there is provided at the originating office a plurality of terminals for each trunk line circuit leading to an adjacent office, a plurality of terminals also being provided thereat for each of the trunk line circuits leading to other offices. Any of the terminals when selected for use causes the automatic association of the trunk with the common apparatus for transmitting codes of current impulses over the common signaling path leading to another office to select the end of the selected trunk terminating thereat. The character of the codes of impulses is also dependent upon the individual terminal of the trunk selected at the originating office and causes the selection of apparatus associated with the trunk at the second office which thereupon functions either to display a signal before the operator, for a connection terminating thereat, or to find an idle trunk circuit leading to a selected one of a plurality of other offices and to automatically connect such trunk to the selected trunk as determined by the connecting terminal employed by the originating operator.

In accordance with another feature of the invention the trunk circuit being employed is temporarily associated with the common signaling path joining the adjacent offices interconnected in this manner for the purpose of transmitting code impulses of current to control the supervisory signals associated with the originating and terminating ends of the sectionalized trunk circuit without producing any signals at the intermediate offices.

In accordance with a further feature of the invention the apparatus at the intermediate office, which selects the trunk leading to the terminating office in response to the selecting impulses received over the common signaling path from the originating office,

also introduces a repeater set associated with the trunk from the originating office between such trunk and the trunk leading to the selected terminating office and simultaneously connects the balancing net-work of the latter trunk with the repeater set.

These and other features of the invention, not specifically mentioned above, will clearly appear from the following specification and 10 the accompanying drawings, Figs. 1 to 7, inclusive, of which, when arranged in accordance with Figs. 9 and 10, show an embodiment thereof in a telephone trunking system and Fig. 8 shows in schematic form the 15 arrangement of the various offices in such a system.

Referring to the drawings, there is shown 20 a toll trunk line L1 comprising two talking conductors extending from a central office U to a central office V. A similar toll trunk extends from the office V to the office W. At the central office U an ordinary toll cord circuit O is located by means of which connection is established with the trunk line L1. The trunk line L1 terminating at 25 office V or office W may be used to connect with the toll switching trunk circuit Q, extending from the terminating position of the central office W to the trunking position 30 where it may connect with a regular subscriber's line T. While only one toll cord circuit, one toll trunk line, one toll switching trunk and one subscriber's line circuit is shown, it is understood that this 35 is for the purpose of convenience only and that many such circuits and lines may be and usually are provided in actual service.

At the office U the trunk line L1 is provided with three jacks 10, 20 and 30. The 40 insertion of the plug 1 of the toll cord O into jack 10 causes the transmission of a code of signaling current impulses over the common signaling path P, extending from office U to office V, to produce a guard signal at the office V associated with the line L1, thereby notifying the operator thereat that a connection has been made with such line. In such a case the call would be extended through the medium of a toll switching 45 circuit Q of the usual type to a subscriber's line such as line T terminating at office V. The insertion of the plug 1 of the toll cord O in the jack 20 causes another code of impulses to be transmitted over the common 50 signaling path P to the office V, however such code selects other apparatus associated with the line L1 at the office V which functions to display the guard signal associated with the line L1 at a distant office, such as office W. In such a case the 55 call is extended at the office W by means of the toll switching trunk Q to a subscriber's line circuit, such as T, terminating thereat.

The insertion of the plug 1 of the toll 60 cord O into the jack 30 at office U causes a

different code signal to be sent over the common signaling path P to the office V where it is received by still different apparatus, causing the line L1 to be extended to another office, such as office Y, as shown in Fig. 8. 70 Similarly the call will be extended from office Y to the subscriber's line circuit T, terminating thereat, by means of a toll switching trunk, such as Q. Also, with additional jacks provided at office U, calls 75 may be extended to other offices similar to W and Y. In any case, the various supervisory signals are transmitted over the common signaling paths from one office to another so that the originating operator has 80 complete control of the local lines inter-connecting adjacent offices or the through toll lines interconnecting widely separated offices and passing through intermediate offices. 85

The signals for the various terminals of each line, as well as the various line circuits, are controlled over a signaling path or conductor P common to the trunk lines, and having a ground return. The signaling conductor is arranged in a well-known manner for the usual duplex operation, there being the usual artificial balancing lines AL and the differential polarized relays 335 and 335' provided at the ends of such path. A commutator is also provided at either end of the path for receiving and sending code signals. These commutators are preferably of the well-known start-type of distributors employed in connection with printing telegraph systems, and it will be understood, are provided with some well-known means (not shown) for maintaining synchronism there-between. 100

The commutator at office U comprises a 105 sending distributor S for transmitting signals over the path P to the office V, and a receiving distributor R for receiving the signals transmitted over the path P from the office V. Similarly, the commutator at the office V comprises a sending distributor S' and a receiving distributor R' for transmitting the signals to and receiving the signals from the office U over the path P. These commutators comprise sending and 110 receiving distributors and are of the same construction. Therefore, a description of one is thought to be sufficient. For convenience, the construction of the sending and receiving distributors S and R, will be described. The sending and receiving distributors each comprise a series of stationary rings, some of which are continuous and others of which are segmented. A shaft 115 common to the sending and receiving distributors at one office, is provided, upon which are mounted the brush arms 319 and 356 normally held against rotation by the respective armatures of two separately controlled release magnets SRM and RRM. 120 125 130

The outer end of each brush arm is insulated from the inner end so that each brush on the arm controls two separate groups of circuits. Between the common shaft and each brush arm a friction clutch mechanism (not shown) is provided by means of which the constantly rotating shaft causes the rotation of each brush arm when released. The face of the sending distributor S is stationary and is provided with a common sending ring 314, a restoring segment *r*, a start segment *s* and individual segments 301 to 306 inclusive, for controlling the character of the signals transmitted over the signaling path P. A common ring 315 is also provided, and segments 316, 317 and 318 are employed for controlling local circuits. The face of the receiving distributor R is also stationary and is provided with a common receiving ring 355 and individual receiving segments 361 to 366 inclusive, for selecting circuits according to the codes of signals received over the signaling path P. The segments 350 to 354 are also provided for controlling the local circuits and the circuits of the release magnet.

At the office U the common signaling path or conductor P is connected to the common sending segment 314, while the alternate contact of the differential polarized relay 335 thereat is connected with a receiving segment 352 in such a manner that when the relay 335 is operatively energized, the release magnet RRM is energized to release the brush 356. At the central office V, the common conductor P is connected with the common sending segment 314', while the normal contact of the differential polarized relay 335' thereat is connected with a common receiving segment 368' of the receiving distributor R'. The alternate contact of the relay 335' is connected with the segment 352', so that when the relay 335' is operatively energized the release magnet R'RM is energized to release the brush 356'.

The signals transmitted over the common conductor P by the sending distributors S and S', are determined by the polarity of current connected with the individual sending segments of the respective sending distributors S and S'. These polarities are determined by the position of the brushes of the various levels of the automatic selector switches SS and SS', provided at the respective offices U and V. These automatic selector switches, which are common to a plurality of trunk lines, are similar in structure, the automatic selector switch SS being provided with eight banks of contacts and corresponding brushes *a*, *b*, and 321 to 326 inclusive. The brushes are mounted upon a single shaft which is driven by a motor magnet initially controlled by start relay 330, which is connected to start conductor X, common to

the various trunk lines as well as the various terminals of the trunk lines. Brushes 321 to 326 are connected directly with the respective individual sending segments 301 to 306 of the sending distributor S. Brush *a* is connected with one winding of relay 332 which controls the stopping of the motor magnet MM and the energization of the release magnet SRM of the sending distributor S. Brush *b* is connected with a contact of slow releasing relay 333 for the purpose of assisting in the control of the switch, as will appear more fully hereinafter. A release relay 334 is also associated with the switch SS and is controlled by the sending distributor S, as will appear fully in the following description.

A plurality of contacts equal to twice the number of trunk line terminals to which the automatic selector switch SS is common, 85 may be associated with each brush. The contacts associated with the different brushes are mounted at different levels in position to be engaged by the respective brushes as they are rotated by the motor magnet MM. 90 Two correspondingly positioned contacts of all levels are allotted to each trunk line terminal, for example, the first two trunk line terminals may be allotted to the jack 10 of the line L1; the second two contacts to the jack 20 of the line L1, and the third two to the jack 30 of the line L1. Similarly, the corresponding (connecting) terminals of the succeeding lines associated with the common signaling path P will be allotted 95 terminals (not shown) on the selector banks. Thus each line will require six terminals on the various contact banks, but only one set of such contacts is shown for the sake of clearness. The two contacts of the levels 100 *a* and *b* allotted to each trunk line terminal are connected with relays individual to and associated with such terminals. As shown, relays individual to the outgoing end of the trunk line L1 are connected by means 105 of individual signal control leads A10, C10, A20, C20 and A30, C30, and common restoring leads B and D. These signal control leads A10 and C10 are shown as connected with the first two terminals of the level associated with the switch *a*, and the other signal control leads A20, A30, C20 and C30 would be associated with the following contacts on the same level. However, they are not shown continuous for the purpose of 110 simplification. The conductors B and D individual to the trunk line and common to the various terminals thereof are connected with the contacts shown for the level *b* in alternate manner so that both conductors 115 are provided for each of the various terminals of the trunk line L1.

The automatic selector switch SS' located at the office V is like the switch SS in structure and is associated in a similar 120

manner with the sending distributor S' . A similar starting relay 330', motor magnet MM' and stopping relays 332', 333' and 334' are also provided. This selector switch is 5 associated with the incoming ends of the trunk lines at the office V by means of individual signal control leads A'10, C'10, A'20, C'20, A'30 and C'30 and the restoring lead B'D'1, as well as the common start 10 lead X'. Individually controlled leads are connected with the contacts of the level a' and the other contacts are connected with the switch in a manner similar to the corresponding leads at office U.

15 In order that signals transmitted from the office U by the sending distributor S and received at the office V, may be utilized, there are provided at the latter office six locking relays 371' to 376' inclusive, having 20 energizing windings connected with the respective individual receiving segments 361' to 366' of the receiving distributor R' . When a signal of negative polarity is transmitted from the particular individual sending segment, the locking relay connected with the corresponding individual receiving segment will be energized and locked. The locking relays control a plurality of receiving and selecting relays 380' to 394' inclusive, which cooperate with locking relays 371' to 375' to select the signal control conductor individual to a desired trunk line or trunk line terminal, while locking relay 376' controls the polarity of the current 30 connected to such conductor. The individual signal control circuits or conductors are connected with the various contacts of relays 387' to 394' inclusive. Similar equipment is provided for the receiving distributor at the office U for utilizing signals transmitted from the offices V and W or Y respectively. Having in mind this brief description of the apparatus of the system shown in the drawings, it is thought that the 35 invention will be more thoroughly comprehended from the description of the operation of the system shown.

40 *Connection of a cord circuit with jack 10 of trunk line L1.*

50 The operator at office U, desiring to establish a connection with a telephone line, such as T, terminating at office V, inserts the calling plug 1 of the toll cord O into the jack 10 of the trunk line L1. Relays 11 and 25 thereupon operate over a circuit established from battery through the winding of relay 6, sleeve contacts of plug 1 and jack 10, and the windings of relays 11 and 25 in series to ground. Relay 6, being marginal, does not operate in this circuit and supervisory lamp 7 fails to light at this time. The operation of relay 25 causes the operation 60 of the busy signaling device 4, over an obvious circuit to indicate that the line circuit L1 is being used. Relay 25 also, in opening its right-hand normal contact, prevents the line L1 from being selected upon a call incoming to office U from another office such as office V which is not 70 shown. The operation of relay 11 causes the operation of relay 14 over a circuit extending from battery, through the inner right-hand normal contact of relay 24, the alternative contact of relay 11, the winding 75 of relay 14 and the left-hand normal contact of relay 16 to ground. Relay 14 thereupon locks over an obvious circuit and relay 16 operates over a circuit extending from battery through the left-hand winding thereof and the inner right-hand alternate contact of relay 14 to ground. Relay 16, in operating, locks over an obvious circuit. Relay 14, in operating, connects a ground to the signaling conductor A10, 80 which may be traced from the outer left-hand contact of relay 16, the outer left-hand contact of relay 14, the left-hand normal contacts of relays 15 and 17 and the right-hand normal contacts of relays 18 85 and 22. A ground is also connected to the common start lead X over a circuit extending from ground through the outer right-hand alternate contacts of relays 16 and 14, the right-hand contact of relay 15, and 90 the right-hand normal contact of relay 17. The connection of the ground to the common start lead X causes the operation of start relay 330, which closes an operating circuit 95 for the motor magnet MM, associated with 100 the selector switch SS. The various arms of such selector switch advance step-by-step under the control of the motor magnet until the contact associated with the individual signaling conductor A10 is reached, whereupon, due to the previously traced ground connection for such lead, relay 332 operates 105 through its left-hand winding, and by opening its left-hand normal contact, opens a circuit and stops the operation of motor 110 magnet MM. Relay 332, in operating, locks up through its right hand winding to battery at the contact of relay 334 and closes a circuit for the release magnet SRM of the sending distributor S, which extends from 115 battery through the common ring 315, the brush arm 319, the segment 316, the outer right-hand alternate contact of relay 332 and the winding of release magnet SRM to ground. The attraction of the armature of 120 the release magnet SRM, upon its energization, releases the brush arm 319, which is thereupon rotated through a complete cycle at the end of which the brush arm is stopped in its normal position, as shown. The brush arm 319, in being rotated, first engages the start segment s, thereby connecting positive battery with the common signaling conductor P. The brush then moves out of engagement with the segment 316, opening the 125 130

energizing circuit of and causing the deenergization of release magnet SRM, restoring its armature to the normal position for engagement with the arm 319 upon the completion of its cycle. With the automatic selecting switch SS in engagement with the first of the two contacts allotted to the jack 10 of the trunk line L1, positive current is connected to the first, second, fourth, fifth 10 and sixth levels, associated with the brushes 321 to 326; while negative current is connected with the first contact of the third level only. When the brush arm 319 engages the segment 317, a circuit is completed for 15 relay 333 which extends from battery, through the ring 315, brush arm 319, segment 317 and the winding of relay 333 to ground. The operation of relay 333 establishes a circuit for relay 17 extending from 20 battery through the contacts of relays 334 and 333, the brush arm b and the contact associated therewith, the restoring conductor B connected to such contact, winding of relay 17, the right-hand contact of relay 15, 25 the outer right-hand alternate contact of relay 14 and the outer right-hand alternate contact of relay 16 to ground. The opening of the normal contacts of relay 17 removes ground from the common start conductor X 30 and the individual signaling conductor A10. Relay 17, in operating, also locks over a circuit extending from battery through the alternate contact and winding of relay 17 and from thence over the previously traced 35 energizing circuit therefor. As the brush 319 successively engages the individual sending segments 301 to 306 inclusive, currents of the polarity connected with such segments through the contacts and brush arms 40 of the selector switch SS, are successively connected with the common signaling conductor P. When the brush 319 moves out of engagement with the segment 317, the energizing circuit of slow-release relay 333 45 is open and when the brush engages segment 318 a circuit is formed for the energization of relay 334, which extends from battery through the ring 315, the brush arm 319, the segment 318 and the winding of relay 334 50 to ground. Release relay 334, in operating, opens the locking circuit of relay 332, which was formed upon the operation of such relay and included the right-hand contact thereof. Relay 332 releases and relay 333 is made 55 slow in releasing so that its normal contact remains open until after the opening of the contact of relay 334. As the brush arm 319 disengages the segment 318, release relay 334 is again deenergized. When the 60 brush arm 319 engages the restoring segment r, negative current is connected with the signaling conductor P. The switch SS is now in position to be seized by another trunk line or trunk line terminal since the trunk 65 line terminal of jack 10 is disconnected

therefrom and the sending distributor is in its normal condition.

The connection of the positive current through the start segment s with the signaling conductor P, causes the operation of the differential polarized relay 335' at office V over a circuit extending from positive battery through the segment s, the brush arm 319, the common sending ring 314 and the junction point between the windings of 70 the differential polarized relay 335, thence by one path through the lower winding of relay 335 and the artificial line associated therewith to ground; and by another path through the upper winding of relay 335, 75 conductor P, both windings of the differential polarized relay 335' and the artificial line to ground. The operation of relay 335' causes the operation of release magnet R' RM associated with the receiving distributor R' at office V. The circuit for such magnet may be traced from battery through the alternate contact of relay 335', the segment 352', the brush arm 356', the segment 353' and the winding of release magnet 80 R' RM to ground. The attraction of the armature of such release magnet releases the brush arm 356' which is thereupon rotated through a complete cycle at the end 85 of which it is stopped in its normal position, as shown on the drawing. As the brush arm 356' moves out of engagement with the segments 352' and 353', the release magnet R' RM is deenergized, thereby permitting 90 the restoration of its armature to the normal position in order to stop the brush 356' when it completes its rotation. When the brush arm 356' engages the segment 369' a circuit is completed for relay 367', extending from battery through the ring 355', the brush arm 356', the segment 369' and the winding of relay 367' to ground. The closure of the contact of relay 367' prepares the locking circuits for the various 95 locking relays 371' to 376' inclusive. The 100 armature of the differentially polarized relay 335' remains in its alternate position as long as the positive current is connected with the other end of the conductor P, and is restored to its normal position whenever 105 negative current is connected with the other end of such conductor. The brush arms 319 and 356' are being rotated at the same time and in synchronism so that while the brush arm 319 is engaged with the individual 110 sending segment 303, the armature of the relay 335' is restored to its normal position and brush 356' engages the individual receiving segment 363'. A circuit is thereupon completed, which extends from battery through the normal contact of relay 335', the common receiving segment 368', the brush arm 356', the individual receiving segment 363 and the lower winding of relay 115 373' to ground. The latter mentioned relay 120 125 130

operates due to this circuit and locks over an obvious circuit due to the operation of relay 367'. The closure of the lower contact of relay 373' causes the operation of relays 381' and 382' over a circuit extending from battery, through the windings of relays 382' and 381' in series and the lower contact of relay 373' to ground. When the brush arm 356' engages segments 350' and 351', the 10 signal receiving relay 171 (Fig. 2) operates over a circuit from negative battery 377' through the normal contact of relay 376', the segment 350', the brush arm 356', the segment 351', the normal contact of relay 375', the lower normal contact of relay 380', the lower alternate contact of relay 381', the upper normal contact of relay 383', and upper normal contact of relay 388', the individual receiving conductor E'10, and 15 the left-hand winding of relay 171 to ground. Relay 171 operates and locks through its right-hand winding. Relay 173 also operates in parallel with relay 171 but 20 does not lock on account of the open contact of relay 170 which is not energized until after the locking of relay 171 and the release of relay 173, which release occurs 25 immediately at the termination of the impulse which operates relay 171. The energization of relay 173, at this time, momentarily closes a circuit for relay 167 extending from battery through the right-hand alternate contact of relay 171, left-hand alternate contact of relay 173, and the winding 30 of relay 167 to ground. Relay 167 being slow-to-operate and release, will not have sufficient time to close its alternate contacts before the termination of the impulse which energizes relay 173. Hence, the operation 35 of relay 173 at this time has no effect upon the circuit. The relay 167 and a similar relay 267 (Fig. 4) are indicated as slow-to-operate and release by arrows intersecting their armatures and pointing in the direction 40 that the armatures are slow to move.

Relay 171, in operating, causes the illumination of lamp 180 over a circuit extending from battery through the right-hand alternate contact of relay 171, the right-hand normal contact of relay 156, and lamp 180 to ground. The closure of the left-hand alternate contact of relay 171 connects the supervisory relay 158 in bridge of the talking conductors of the trunk L1, extending 45 toward the plug 151. When the brush arm 356' disengages segments 368' and 366', the energizing circuit of relays 171 and 173 is opened, causing the deenergization of relay 173. Slow release relay 170 is then energized over a circuit extending from battery through the right-hand alternate contact of relay 171, the normal contact of relay 173, and the winding of relay 170 to ground. When the brush arm 356' engages the segments 352' and 353' the armature of relay

335' is in its normal position since the brush arm 319 is connected with restoring segment r. A negative current is, therefore, connected with the common signaling path or conductor P, so that the energizing circuit 70 of release magnet R'RM is opened. The disengagement of the brush arm 356' from the segment 369' and engagement with segment 354' causes the release of relay 367'. Therefore, the locking circuit of relay 373' is 75 opened, allowing the release of such relay and causing the deenergization of relays 381' and 382'. All apparatus associated with the automatic selecting switch SS, the sending distributor S, the receiving distributor R' and the receiving circuit at office V, is now in normal condition so that it may be employed in connection with any other trunk line. The lighting of the lamp 180 80 serves as a guard signal to the operator at the office V indicating that the operator at the office U has connected the toll cord circuit O with the trunk line circuit L1. 85

Connection of toll switching trunk circuit 90 Q with telephone line circuit T.

The operator at office V ascertains from the operator at office U the number of the desired line and then communicates with the toll switching operator at the 95 office V before whom the telephone line circuit T terminates. An order wire (not shown) of the usual type is used for this purpose. The toll switching operator at the office V informs the incoming or receiving operator at the same office that the toll switching trunk Q, leading between the positions of the two operators at the office V, should be employed for extending the connection to the wanted line circuit T. 100 Immediately upon assigning the trunk Q for this purpose the toll switching operator inserts the plug 89 of the toll switching trunk Q into the jack 90 of the desired line circuit T. The cut-off relay 91 of the line circuit 105 and the sleeve relay 88 of the toll switching trunk circuit Q thereupon operate over a circuit traceable from battery through the winding of relay 88, the sleeve contacts of plug 89 and jack 90, through the winding of cut-off relay 91, to ground. The operation of the cut-off relay 91 performs its usual function in removing the line relay 92 from association with the line conductors, thereby preventing the display of the line 110 signal 93 upon the answer of the called party. The opening of the right-hand normal contact of relay 88 disconnects the trunk operator's telephone set testing lead, with which a test has been made, on the line circuit T before the insertion of the plug 89 115 into the jack 90. The closure of the right-hand alternate contact of relay 88 completes the continuity of the tip conductor of the trunk circuit, while the closure of the left- 120

125 130

hand alternate contact of such relay causes the illumination of lamp 87 over a circuit extending from battery through the lamp 87, the left-hand alternate contact of relay 88, the resistance 94, and the normal contact of relay 86 to ground.

Connection of the trunk line circuit L1 with the toll switching trunk circuit Q.

- 10 The operator at office V, upon observing the lighted condition of the lamp 180, inserts the plug 151 of the trunk line L1 into jack 80 of the toll-switching trunk Q. Relay 152 thereupon operates over a circuit 75 extending from battery through the winding of relay 152 and the sleeve contacts of plug 151 and jack 80 to ground. The operation of relay 152 causes the operation of relay 156 over an obvious circuit, and the 80 opening of the right-hand normal contact of such relay extinguishes the lamp 180. The closure of the left-hand alternate contact of relay 156, completes the tip conductor of the trunk line L1, while the opening of 85 the left-hand normal contact disconnects the operator's telephone testing lead from such conductor.

The supervisory relay 158 of the trunk line L1 and relay 86 of the toll-switching 90 trunk Q operate over a circuit extending from battery through the left-hand winding of relay 86, the left-hand normal contact of relay 84, the ring contacts of jack 80 and plug 151, the right-hand normal contact of 95 relay 155, the right-hand normal contact of relay 154, the left-hand alternate contact of relay 171, the winding of relay 158, the right-hand normal contact of relay 157, the left-hand normal contacts of relays 154 and 155, the left-hand alternate contact of relay 156, the tip contacts of plug 151 and jack 80, the right-hand normal contact of relay 84 and the right-hand winding of relay 86 to ground. The energization of relay 86 100 extinguishes the lamp 87.

The energization of supervisory relay 158 causes the energization of relays 159, 160 and 161, the energizing circuit for relay 159 extending from battery through the winding of relay 159 and the alternate contact of relay 158 to ground. The circuit for relay 160 may be traced from battery through the winding of relay 330', the common start conductor X', the inner 115 right-hand normal contact of relay 165, the winding and right-hand normal contact of relay 160, the normal contact of relay 161, the left-hand contact of relay 165, the outer left-hand contact of relay 169 and the right-hand alternate contact of relay 158 to ground. The relay 161 energizes in the circuit extending from battery through the winding and right-hand normal contact of relay 161 and from thence in parallel over 120 the energizing circuit of relay 160. Relay 125 130

160 in energizing is locked over an obvious circuit including the conductor X' and relay 161 completes a locking circuit for itself from battery through the winding and right-hand alternate contact of relay 161, 70 the right-hand normal contact of relay 162, the left-hand normal contact of relay 169 and the alternate contact of relay 158 to ground. The closure of the left-hand alternate contact of relay 160 establishes a 75 circuit extending from ground through said contact, the normal contact of relay 164, the winding of relay 166, the normal contact of relay 157 and the right-hand alternate contact of relay 171 to battery. Relay 166 energizes and locks through its winding and contact, the winding of relay 164 to ground at the inner normal contact of relay 169. Relay 164 is not energized in this locking circuit during the 80 operation of relay 160, since relay 164 is short-circuited by the ground at the left-hand alternate contact of relay 160 and the inner normal contact of relay 169. Relay 160, in closing its outer right-hand alternate contact, grounds the signal control conductor A'10 connected with the 85 first of the two contacts on the level associated with brush a' of the automatic selecting switch allotted to the trunk terminal 10 of line L1. Start magnet 330' is energized in the circuit through its winding, above described, and completes an operating circuit for motor magnet MM' associated with the selector switch SS'. This 90 motor magnet, which is of the self-interrupting type, well known in the art, thereupon advances the brushes of the switch step by step until the brush a' engages the contact to which the signal control conductor A'10 is connected, whereupon relay 332' is operated over a circuit extending from battery through the right-hand winding of relay 332', the brush arm a' and the contact associated therewith, the signal control conductor A'10, and the right-hand alternate contact of relay 160 to ground. The relay 332', in operating, opens the 100 circuit of motor magnet MM', thereby stopping the switch SS' in that position. A 105 locking circuit is provided for the relay 332', which extends from battery through the contact of relay 334', the inner left-hand alternate contact and left-hand winding of relay 332' to ground. The sending distributor S' thereupon functions to successively connect with the common signaling conductor P currents of the polarities connected with the individual sending segments 301' to 306' of this distributor. To 110 the restoring segment r' negative current is permanently connected, while positive current is permanently connected with the start segment s'. Since the terminal 10 of the trunk line L1 is now involved, posi-

tive current is connected with segments 301', 302', 304', 305' and 306'; while negative current is connected with segment 303'. While brush arm 319' is making a complete cycle, the release magnet SRM' is deenergized when said arm moves out of engagement with the segment 316'. The circuit of slow-releasing relay 333' is closed during the time the brush is in engagement with segment 317', and the release relay 334' is energized during the time the brush engages segment 318'. When relay 333' energizes a circuit is established for relay 165 extending from battery through the contacts of relays 334' and 333', brush arm b', conductor B'D'1 and the winding of relay 165 to ground. The operation of relay 165 opens the locking circuit and causes the release of relay 160, thereby removing ground from the conductor A'10. Relay 165 also disconnects battery from the start conductor and upon the release of relay 160, the short circuit is removed from the winding of relay 164 and said relay then operates in the locking circuit for relay 166. The operation of relay 164 has no effect at this time. The apparatus associated with the sending distributor S' and the automatic selecting switch SS' now functions in the same manner as that associated with the sending distributor S and the automatic selecting switch SS. Relay 165 becomes deenergized upon the release of relay 333' which follows the disengagement of the brush arm 319' from the segment 317'. The differentially polarized relay 335, connected with the common signaling conductor P at the office U, operates when the brush arm 319' engages the start segment s', whereupon the release magnet RRM of the receiving distributor R at the office U is energized to release the brush arm 356. When the brush arm 319' engages the sending segment 303', the relay 335 is deenergized, whereupon relay 373 operates over a circuit extending from battery through the normal contact of relay 335, the segment 368, the segment 363 and the lower winding of relay 373 to ground. Relay 373 thereupon locks over a circuit extending from battery through the upper winding and upper contact of relay 373 and the contact of relay 367 to ground, since relay 367 operates as soon as the brush arm 356 engages the segment 369 and maintains the latter relay energized throughout the selecting operation of the receiving distributor. Relays 381 and 382 thereupon operate over a circuit extending from battery through the windings of such relays in series, and the lower contact of relay 373 to ground. When the arm 356 engages segments 350 and 351, battery is connected in circuit with relay 25 over a path which may be traced as follows: from battery 377 through the lower normal contact of relay 376, segment 350, arm 356 and segment 351 of the receiving distributor R, the normal contact of relay 375, the lower normal contact of relay 380, the lower alternate contact of relay 381, the upper normal contact of relay 383, the upper normal contact of relay 388, the signal-receiving conductor E10, and the left-hand winding of relay 26 to ground. Relay 26 thereupon operates and locks through its right-hand winding, the alternate contact of relay 11 and thence to battery through the inner right-hand normal contact of relay 24. At the time of the energization of relay 11, a circuit was established for relay 32 extending from ground at relay 26 through the winding of relay 32 and from thence over the locking circuit just described for relay 26. The energization of relay 32 prevents the operation of relay 33 when relay 26 is energized. The closure of the left-hand alternate contact of relay 26 completes a circuit from battery through the winding of relay 6 of the toll cord circuit O, the sleeve contacts of plug 1 and jack 10, the left-hand normal contacts of relays 19 and 23, the resistance 35, the right-hand normal contact of relay 24, the left-hand alternate contact of relay 26, and the left-hand normal contact of relay 33 to ground. The resistance of this circuit is such that the marginal relay 6 operates to cause the lighting of the supervisory lamp 7 over an obvious circuit, thereby notifying the operator that the connection has been established with the desired line circuit T and that such circuit is in condition for signaling the substation on the line.

The operator at office U actuates the ringing key.

The operator at office U, upon observing the lighted condition of the supervisory lamp 7, may actuate the ringing key 2, which connects the source of ringing current with the talking conductors of the cord circuit O and the associated trunk line L1. Ringing response relay 13 is operated, thereby causing the energization of relay 15 over a circuit extending from battery through the winding of relay 15 and the contact of relay 13 to ground. Relay 17 is thereupon deenergized by the opening of its locking circuit and the conductor X is disconnected from ground by the operation of relay 15.

Operator at office U releases the ringing key.

Upon the restoration of the ringing key 2 of the cord circuit O to its normal position, relay 13 releases causing the deenergization of relay 15, which in deenergizing connects ground to conductor A10, which may be traced from ground through the outer left-hand alternate contact of relay 16, the outer left-hand alternate contact

of relay 14, the left-hand normal contacts of relays 15 and 17, and the right-hand normal contacts of relays 18 and 22. At the same time conductor X is grounded in 5 the same manner as previously described. Relay 330 thereupon operates to cause the operation of the motor magnet MM of the selector switch SS, whereupon the same sequence of operations of the selector switch 10 SS occur as previously described in connection with the transmission of the guard signal from the station U to the station V. In a similar manner the sending distributor S and the receiving distributor R' function 15 as described and the receiving conductor E'10 is selected as previously mentioned. Relay 171 is unaffected by the polarity of current flowing over the selected lead upon the transmission of the 20 final impulse over such lead, since the polarity of such current is such as to maintain said relay in an operated condition. However, relay 173 is operated over a circuit traced in parallel with that of the left-hand 25 winding of relay 171, and relay 173 is thereupon momentarily locked over a circuit extending from battery through the right-hand winding and right-hand alternate contact of relay 173 and the contact of relay 30 170 to ground. Upon the operation of relay 173, all the apparatus associated with the sending distributor S and receiving distributor R' is restored to normal as previously mentioned. The closure of the 35 left-hand alternate contact of relay 173 causes the operation of relay 167 over a circuit extending from battery through the right-hand alternate contact of relay 171, the left-hand alternate contact of relay 173 and the winding of relay 167 to ground. 40 Relay 167 has sufficient time to close its contacts in this instance since relay 173 is held operated by the slow-release relay 170 for a longer period of time than the duration 45 of the impulse received over the conductor E'10. The closure of the left-hand contact of slow-operate and release relay 167 completes a circuit for ringing relay 155, which extends from battery through the winding 50 of relay 155, and the left-hand contact of relay 167. Slow release relay 168 is also operated over an obvious circuit by the closure of the left-hand contact of relay 167. The closure of the right-hand contacts 55 of relays 167 and 168 also connect ground to the winding of relay 159 which is already energized under the control of relay 158. Relay 155, in operating, closes a circuit extending from the source of ringing 60 current 181, through the right-hand alternate contact of relay 155, the ring contacts of plug 151 and jack 80, the winding of relay 81, the condenser 82, the tip contacts of jack 80 and plug 151, the left-hand alternate contact of relay 156, and the left-hand 65

alternate contact of relay 155 to ground. Relay 81 thereupon operates during the continuation of current flowing over this circuit and causes the operation of relay 84 and ringing relay 85 over a circuit extending from battery through the left-hand winding of relay 84, the winding of relay 85 and the contact of relay 81 to ground. The operation of relay 84 maintains the relay 86 energized. Relay 85, in operating, causes the completion of a circuit extending from a source of alternating current through the right-hand alternate contact of relay 85, the ring contacts of plug 89 and jack 90, the subscriber's station on the line circuit T, the tip contacts of jack 90 and plug 89, the right-hand alternate contact of relay 88 and the left-hand alternate contact of relay 85 to ground. The bell at the subscriber's station is thereupon operated to notify the subscriber that a call awaits his answer. 70 75 80 85

As soon as slow-release relay 170 has fully restored to normal, relay 173 is released due to the opening of the locking circuit, previously traced therefor, whereupon slow-operate and release relay 167, and slow-release relay 168 release, and upon the complete release of relay 167, ringing relay 155 releases to remove the ringing current from the line circuit L1 and the connected toll switching trunk circuit Q. Although the release of relays 167 and 168 breaks two connections to ground for the winding of relay 159, this relay is not deenergized as 90 a third ground connection is still maintained at the contacts of relay 158. Upon the cessation of such ringing current, ringing response relay 81 releases, causing the subsequent release of relay 84 and ringing 95 relay 85 of the trunk circuit Q to remove the ringing current from the line circuit T and to restore the apparatus of the toll switching trunk circuit to the condition in which it appeared prior to the sending of 100 the ringing signal from the station U. The apparatus associated with the trunk line L1 is also restored to the same condition as before. Thus each time the ringing key of the cord circuit O at the station U is actuated 110 and released, the same series of operations occur and as a consequence the signaling bell at the substation on the line circuit T is actuated for an interval. 115 120 125 130

Subscriber at the station on the telephone line circuit T removes the receiver from the switchhook.

The subscriber at the station on the telephone line circuit T, when responding to the operation of the signal, removes the receiver from the switchhook, thereby causing the operation of the supervisory relay 83 over a circuit extending from battery through the winding of relay 83, the upper 130

- right-hand winding of repeating coil 95, the right-hand normal contact of ringing relay 85, the ring contacts of plug 89 and jack 90, the apparatus at the station on the line circuit T, the tip contacts of jack 90 and plug 89, the right-hand alternate contact of relay 88, the left-hand normal contact of relay 85 and the lower right-hand winding of the repeating coil 95 to ground.
- 10 Supervisory relay 83, in operating, causes the energization of relay 84 over a circuit extending from battery through the left-hand winding of relay 84, the contact of the supervisory relay 83, the right-hand winding of relay 84, and the alternate contact of relay 86 to ground. Relay 84, in operating, closes its alternate and opens its normal contacts, whereby relay 86 is disconnected from the circuit including the supervisory relay 158 of the trunk line circuit L1 connected with the toll switching trunk Q. However, relay 86 is maintained operated due to the circuit formed, which may be traced from battery through the left-hand winding of relay 86 and the left-hand alternate contact of relay 84 to ground. Relay 84 in operating, also causes the deenergization of the supervisory relay 158, due to the opening of the circuit thereof. Relay 158, in opening its alternate contact, opens the energizing circuit of slow-release relay 159 and the locking circuit of relay 161. Relay 159 is slow in releasing so that before it releases its armature, relay 163 is operated over a circuit extending from battery through the winding of relay 163, the alternate contact of relay 159 and the normal contact of relay 158 to ground. However, the operation of relay 163 performs no useful function at this time. Upon the closure of the normal contact of relay 159, relay 169 operates over a circuit extending from battery through the winding of start relay 330', the starting conductor X', the outer right-hand normal contact of relay 165, the winding of relay 169, the left-hand normal contact of relay 160, the right-hand alternate contact of relay 164 which is now operated due to the release of relay 160, the normal contact of relay 159, and the normal contact of relay 158 to ground. Relay 169, in operating, locks through its winding and left-hand alternate contact to ground. The operation of relay 169 causes the release of relays 164 and 166. The closure of the right-hand alternate contact of relay 169 grounds the signal control conductor C'10 which is connected to the second of the two contacts on the level a' of the selector switch SS', which are allotted to the jack 10 of the trunk line L1, extending from the station U to the station V. The energization of the start relay 330' causes the operation of motor magnet MM' of the selector switch SS',

whereupon the switch advances step by step 65 until the brush a' engages the contact to which the signal control conductor is connected. Relay 332' thereupon operates over an obvious circuit and locks in the manner previously described to stop the motor magnet MM'.

The brushes of the selector switch SS', engaging the second set of contacts allotted to the jack 10, connects a current of positive polarity with the individual sending segments 301', 302', 304' and 305' and connects current of negative polarity to the individual sending segments 303' and 306'. The energization of relay 332' energizes release magnet SRM' associated with the sending distributor S', whereby the brush 319' is released and makes a complete revolution to transmit over the common signaling conductor P a combination of impulses or code signals determined by the polarities connected with the individual segments of the sending distributor, as controlled by the position of the arms of the selector switch SS'. When the brush arm 319' engages segment 317', relay 333' energizes and relay 165 90 thereupon operates over the previously described circuit therefor. The operation of relay 165 deenergizes relay 169. When the combination of impulses has been transmitted in the manner described in the previous 95 instance, the sending distributor S' and the automatic selector switch SS', as well as all other associated sending apparatus, are restored to normal and the relay 165 is released. These transmitted impulses, being 100 received at office U, cause the energization and locking up of relays 373 and 376 when the brush 356 of the receiving distributor R engages the segments 363 and 366. The operation of relay 373 causes the energization 105 of relays 381 and 382 in the manner hereinbefore described to select the conductor E10, leading to the apparatus associated with the jack 10 of the trunk line L1. However, the operation and locking of relay 376 causes 110 current of a different polarity to be sent over such receiving conductor when the brush 356 engages the segments 350 and 351. This current is of such polarity as to differentialize and thus cause the release of 115 relay 26 when it flows through the left-hand winding of such relay. The relation of the number of turns of the two windings of signal receiving relay 26 is such that when positive polarity traverses the left-hand or 120 energizing winding at the same time that current of a different polarity traverses the locking or right-hand winding, the relay is differentialized and releases its armatures. The opening of the left-hand alternate contact of relay 26 disconnects resistance 35 from its parallel relation with the winding 125 of relay 11, whereupon the marginal relay

6 of the cord circuit O releases its armature and extinguishes the supervisory lamp 7, whereupon the apparatus at the office U is restored to the same condition as existed 5 prior to the insertion of the plug 1 into the jack 10. The extinguishment of the lamp 7 serves as a signal to the operator at the office U that the desired subscriber has responded to the call.

10 *Subscriber restores the receiver to the switchhook.*

At the conclusion of the conversation, the subscriber at the station on the telephone 15 line circuit T restores the receiver to the switchhook, thereby releasing supervisory relay 83, which opens the circuit of the release relay 84. Relay 86 is thereupon connected in circuit with supervisory relay 158 20 to cause the energization of the latter relay. Prior to the energization of supervisory relay 158, all of the relays individual to the trunk line L1 at station V which are controlled by such supervisory relay, are de- 25 energized. The energization of supervisory relay 158 causes the operation of relays 159, 160 and 161 in the manner before described, to thereby cause the movement of the automatic selector switch SS' until its brush a' 30 engages the grounded signal control conductor A'10, and the sending distributor S' transmits over the conductor P the same combination of impulses as when the plug 151 was inserted into the jack 80 of the toll 35 switching trunk circuit Q. The operation of relay 160 also causes the operation of relay 166 and the short-circuiting of relay 164 as before described. Relay 165 operates when relay 333' is energized and re- 40 leases relay 160. Following the release of relay 160, relay 164 operates in series with relay 166. Upon the return of the sending distributor S' to normal position and the release of relay 160, the automatic selector 45 switch SS' and the sending distributor S' are removed from their operative association with the trunk line L1 and may there- 50 after be temporarily associated with any other trunk line or terminal thereof. The transmitted combination of impulses, when 55 received at the office U through the action of differentially polarized relay 335 and the receiving distributor R, thereby causes the energization of relays 373, 381, and 382, as previously mentioned, as well as the energization and the locking of signal receiving 60 relay 26, in the manner previously described in detail. Resistance 35 is again connected in parallel with the winding of relay 11 to permit the operation of marginal relay 6 and the consequent display of a disconnect signal by the illumination of lamp 7. Following the energization of the signal-receiving 65 relay 26, the brush 356 of the receiving

distributor R is stopped in its normal position and relay 367 is released to cause the release of relays 373, 381 and 382.

Operator at office U disengages the toll cord circuit O from the jack 10 of the trunk line L1.

The operator at office U, upon observing the lighted condition of the supervisory lamp 7, withdraws the plug 1 from the jack 10, causing the release of relays 11, 6, 25 70 and 14. The release of relay 6 opens the circuit of and extinguishes the supervisory lamp 7. The release of relay 14 causes the energization of the start magnet 330 over a circuit extending from battery through the winding of start magnet 330, the start conductor X, the outer right-hand normal contact of relay 14 and the outer right-hand alternate contact of relay 16 to ground. The deenergization of relay 14 also grounds the signal control conductor C10 over a connection which may be traced from ground through the outer left-hand alternate contact of relay 16, and the left-hand normal contacts of relays 14, 18 and 22. Thus the second of the two contacts of the level a of the selector switch SS allotted to the jack 10 of the trunk line L1 is grounded. Motor magnet MM thereupon functions when start relay 330 is energized over the circuit previously traced therefor, to advance all of its brushes until the brush a engages the contact to which the signal control conductor C10 is connected, whereupon relay 332 operates and locks as well as opens the circuit of the motor magnet and stops the operation of the switch SS. The brushes 321, 322, 324 and 325 of the selector switch SS now connect positive current with the individual sending segments 301, 302, 304 and 305 of the sending distributor S, while brushes 323 and 326 connect current of negative polarity to the sending segments 303 and 306 respectively of the sending distributor S. The closure of the outer right-hand alternate contact of relay 332 energizes the release magnet SRM of the sending distributor S, thereby releasing the brush arm 319, which, in making a complete revolution, transmits over the common signaling conductor P a combination of impulses corresponding to the polarities of current connected with the individual sending segments of the sending distributor. When the brush 319 engages segment 317 110 relay 333 is operated. A circuit is thereupon completed from battery through the contacts of relays 334 and 333, the brush b, the restoring conductor D and the inner right-hand alternate contact and right-hand winding of relay 16 to ground. This relay thereupon becomes differentialized and releases its armatures. The impulses trans-

mitted by the distributor S are received at the office V by the differential polarized relay 335' and the receiving distributor R' to cause the energization and locking of relays 373' and 376', as well as the operation of relay 367'. Relays 381' and 382' operate upon the energization of relay 373' so that when brush 356' engages the segments 350' and 351', the signal receiving relay 171 is 5 differentialized due to the character of the current flowing through its left-hand winding, as previously described in connection with the releasing of relay 26 at the station U. The circuit for causing the release of 10 relay 171 may be traced from positive battery 378' through the lower alternate contact of relay 376', segments 350' and 351', the brush arm 356' of the receiving distributor R', the lower normal contact of 15 relay 375', the lower normal contact of relay 380', the lower alternate contact of relay 381', the upper normal contact of relay 383', the upper normal contact of relay 388', the receiving conductor E'10 and the left-hand winding of relay 171 to ground. Relay 171 thereupon releases its armatures, and the opening of its right-hand alternate contact causes the release of relays 166 and 164, while the closure of the right-hand normal 20 contact of relay 171 causes the illumination of lamp 180 over a circuit extending from battery through the normal contact of relay 171, the right-hand alternate contact of relay 156 and the lamp 180 to ground. The lighting of the lamp 180 serves as a disconnect signal to the operator at the office V. The opening of the left-hand alternate contact of relay 171 opens the circuit including the supervisory relay 158 of the trunk 25 line L1 and the relay 86 of the toll switching trunk circuit Q, whereupon both of these relays release. The opening of the alternate contact of supervisory relay 158 restores relays 159 and 161 to normal condition. Relay 30 163 is energized after the release of relay 158 and before the release of relay 159, but is deenergized when slow-release relay 159 is completely deenergized. The energization of relay 163 does not, at this time, perform any useful function. The release of relay 86 of the toll switching trunk Q, causes 35 the lighting of lamp 87 over a circuit extending from battery through the lamp 87, the left-hand alternate contact of relay 88, the resistance 94, and the normal contact of relay 86 to ground. The lighting of the lamp 87 now serves as a disconnect signal to the toll switching operator at whose position the toll switching trunk circuit Q terminates. The terminating operator and the toll switching trunk operator at office V 40 may, upon observing the lighted condition of the respective supervisory lamps 180 and 87, withdraw the plugs 151 and 89 from the

jacks 80 and 90 respectively, thereby restoring all apparatus to its normal condition. 65

Subscriber at the station on the telephone line T terminating at office V recalls the operator at office U. 70

Should the subscriber at the station on the trunk line T, after answering a call when the connection is established between the toll cord circuit O and the telephone line T by means of the jack 10 of the trunk line L1 extending between the office U and V as well as the toll switching trunk Q, desire to recall or signal the operator at office U, this result may be accomplished by repeatedly opening and closing the switchhook contact at the station on the line circuit T. 75 From the previous description it is evident that while the receiver at the station on the line circuit T is removed from the switchhook so that the switchhook contact thereat is closed, supervisory relay 158 and all relays 159 to 166 and 169, controlled by such supervisory relay, are deenergized. 80 All the other relays associated with the incoming end of the trunk line L1 at the office V, the signal receiving relay 171 and slow release relay 170 and relay 156 are energized, while the signal-receiving relay 173, the ringing relay 155 and the slow 85 releasing relays 167 and 168 are deenergized. Relay 159 is made slow in releasing so that its alternate contact will be maintained in a closed condition during the short periods when the alternate contact of 90 the supervisory relay 158 is opened during the period that the subscriber at the station on the line circuit T is repeatedly opening and closing the switchhook contact thereat to signal the operator at the office U. Similarly, relay 163 is made slow in releasing 95 so that it is maintained operated during the short period when the normal contact of the supervisory relay 158 is opened. Relays 162, 166 and 164 are also made slow 100 in releasing to assist in the control of the recall signal before the operator at the office U, when the subscriber at the station on the telephone line T is recalling the operator thereat. 105

Upon the first opening of the switchhook contact the supervisory relay 158 is energized, thereby energizing the relays 159, 160, 161 and 166, as previously described; 110 also the automatic selector switch SS' advances until the brush a' engages the contact to which the individual signal control conductor A'10, temporarily grounded, is connected, when relay 332' operates. The 115 operation of relay 332' energizes release magnet SRM', whereupon the sending distributor S' transmits over the common conductor P a combination of impulses deter- 120

mined by the polarities connected with the individual sending segments 301' to 306' respectively. During the operation of the distributor S', relay 165 is operated as previously described to deenergize relay 160, following which relay 164 is energized and locked. The receiving distributor R at the office U functions upon the reception of these transmitted impulses by means of the 10 relay 335 to cause the temporary energization of relay 367 and the temporary energization of relays 373, 381 and 382, whereby the signal-receiving relay 26 is energized and locked. The marginal relay 6 of the 15 cord circuit then operates to cause the illumination of the supervisory lamp 7 and relay 32 is deenergized upon the operation of the signal-receiving relay 26.

The closure of the switchhook contact 20 shortly after the opening thereof, causes the deenergization of the supervisory relay 158, which causes the immediate deenergization of relay 161 and the energization of relay 163. The subsequent energization of 25 the supervisory relay 158 in response to the next opening of the switchhook contact, causes relays 160 and 161 to operate in the order named, as previously described. Upon the operation of relay 160, relay 162 30 is energized over a circuit from battery through the right-hand alternate contact of signal-receiving relay 171, the left-hand normal contact of relay 157, the winding and inner right-hand normal contact of 35 relay 162, the left-hand alternate contact of relay 164 which was energized when relay 160 released during the transmission of the first series of impulses which resulted in the lighting of the lamp 7, and the inner 40 left-hand alternate contact of relay 160 to ground. Relay 162 immediately locks through its inner right-hand alternate contact and the inner left-hand normal contact of relay 169 to ground. Upon the 45 energization of relay 162, relay 161 is locked over a circuit which may be traced from battery through the winding and alternate contact of relay 161, the outer right-hand alternate contact of relay 162 and from 50 thence to ground at the inner normal contact of relay 169, whereby relay 161 is removed from the control of the supervisory relay 158 during the rapid actuations thereof, while the switchhook contact is being rapidly opened and closed to signal the operator at the office U. The energization of 55 relay 160 causes the automatic selector switch SS' to start the sending distributor S', which transmits over the common signal conductor P a combination of impulses corresponding to the terminal jack 10 of the trunk line L1 and determined by the brush a', which connects with the temporarily 60 grounded signal control conductor A'10.

The reception of these impulses by the relay 335 at office U causes the receiving distributor R to function to cause the temporary energization of relay 367 and the temporary energization of relays 373, 381 and 382 as before. When the brush 356 engages segments 350 and 351, signal-receiving relay 33 operates over a circuit from negative battery 377, the segments 350 and 351 in co-operation with the arm 356 of the receiving distributor R, the lower normal contact of 65 relay 375, the lower normal contact of relay 380, the lower alternate contact of relay 381, the upper normal contact of relay 383, the upper normal contact of relay 388, the signal-receiving conductor E10, the normal 70 contact of relay 32, and the left-hand winding of signal-receiving relay 33 to ground. Relay 33, in operating, completes a locking circuit for itself extending from battery 75 through the inner right-hand normal contact of relay 24, the alternate contact of relay 11 and the right-hand winding and right-hand alternate contact of relay 33 to ground. The closure of the left-hand alternate contact of relay 33 connects interrupter 80 85 90 95 100 105 110 115 120 125 34 in series with the left-hand alternate contact of relay 26 and the resistance 35, thereby furnishing a grounded circuit through such resistance which is in parallel relation with the winding of relay 11. The alternate shunting of the winding of relay 11, caused by the intermittent ground furnished through the interrupter 34, causes the intermittent operation and deenergization of marginal relay 6 to flash the supervisory lamp 7 at a predetermined rate, depending upon the speed at which the interrupter 34 operates. The intermittent lighting of the lamp 7 serves to indicate that the subscriber at the station on the line circuit T desires to recall the operator at the office U. This recall signal is repeated after the second opening of the switchhook contact of the station on the line circuit T. No more signals are transmitted over the signaling path during the continued opening and closing of the switchhook contact. The signal is produced at a constant rate and is easily observed by the operator. However, it is necessary to continue to open and close the switchhook contact to maintain the signal in connection with the interrupter 34.

If, after repeatedly opening and closing the switchhook contact to signal the operator at the office U, the subscriber at the station of the telephone line circuit T should leave the switchhook contact closed, then the supervisory relay 158 is deenergized. After the comparatively extended deenergization of this relay, relays 159 and 163 release and upon the closure of the normal contact of relay 163, relay 169 operates over a circuit through the left-hand contact of

relay 162, and the energization of relay 169 releases relays 161, 162, 166 and 164. The operation of relay 169 also grounds the signal-control conductor C'10, and the start magnet 330' is again energized. The selector switch SS' thereupon functions and the brushes are advanced step by step until brush a' engages the contact to which the grounded signal control conductor C'10 is connected. Then the control apparatus associated with the selector switch and the sending distributor S' causes the transmission of the same combination of impulses which was transmitted when the receiver at the station on the telephone line T was removed from the switchhook upon the response of the subscriber to the calling signal. The reception of the transmitted impulses at the office U, causes the transmission of an impulse from battery through the signal-receiving conductor E10 to differentialize the signal-receiving relays 26 and 33, thereby the interrupter 34 is disengaged from circuit relation with the marginal relay 6. Such relay thereupon opens its contact and extinguishes supervisory lamp 7. Relay 32 operates upon the deenergization of relay 26.

If, after repeatedly opening and closing the switchhook contact, the subscriber should leave the switchhook contact open, the supervisory relay 158 would be energized. An extended energization of such relay causes the deenergization of relay 163 which, upon the closure of its contact, causes the energization of relay 169. The selector switch SS' and the sending and receiving distributors S' and R thereupon function in the manner previously described for causing the differentialization and the release of the signal-receiving relays 26 and 33 to disconnect interrupter 34 from its circuit relation with the marginal relay 6. Following the release of relay 169, due to the energization of relay 160 as before described, relay 160 is operated over the conductor X' and through contacts of relays 165, 161, 169 and 158. Relay 160 locks and relay 161 operates shortly after the energization of relay 160 to open the original energizing circuit of the latter relay. The energization of relay 160 results, in the same manner as described in connection with the disconnect signal, in the operation of the selector switch SS' and the sending and receiving distributors S and R for sending and receiving a combination of impulses corresponding to the polarities connected with the individual sending segments 301' and 306', the polarities being first connected with the contacts of the first of the six levels of the switch SS' allotted to the jack terminal 10 of the trunk line L1. Upon the reception of these impulses by the differentially polarized relay 335, the receiv-

ing distributor R functions to cause the energization and locking of the signal-receiving relay 26, whereupon marginal relay 6 operates to illuminate the supervisory lamp 7, which now serves as a disconnect signal to the operator at office U. 70

THROUGH CALLS.

The operator at office U plugs into jack 20 of trunk line L1 to extend a call to the line circuit T, terminating at office W. 75

Assuming that the operator at office U desires to extend a connection to a station on line circuit T, terminating at office W, which must be reached through office V and 80 the toll switching trunk Q at office W, the plug 1 of the cord circuit O is inserted into jack 20 of the line L1, which has been found to be idle. Relays 21 and 25 thereupon operate over a circuit extending from battery through the winding of relay 6, sleeve contacts of plug 1 and jack 20, the windings of relays 21 and 25 in series, to ground. Relay 6 is marginal and receives insufficient current over this circuit to cause its operation. Relay 25, in operating, causes the operation of the usual busy signal 4 over an obvious circuit. Relay 21, in operating, causes the operation of relay 14 over a circuit extending from battery through the left-hand alternate contact of relay 21, the winding of relay 14 and the normal contact of relay 16 to ground. Relay 32 also operates over a circuit extending from battery through the left-hand alternate contact 95 of relay 21, the winding of relay 32 and the normal contact of relay 26 to ground. The operation of relay 14 causes the operation of relay 16 over a circuit extending from battery through the left-hand winding of relay 16 and the inner right-hand alternate contact of relay 14 to ground. Relay 14 also locks over a circuit extending from battery through the left-hand alternate contact of relay 21 and the winding and inner left-hand alternate contact of relay 14 to ground. Relays 18 and 19 also operate over a circuit extending from battery through the inner right-hand normal contact of relay 24, the normal contact of relay 11, the right-hand alternate contact of relay 21, the normal contact of relay 31, the windings of relays 19 and 18 in series, and the inner right-hand alternate contact of relay 14 to ground. Relay 19 thereupon locks over a circuit extending from battery through the right-hand alternate contact and the winding of relay 19, the winding of relay 18 and the inner right-hand alternate contact of relay 14 to ground. The closure of the outer right-hand alternate contact of relay 16 completes a ground connection to start conductor X, which extends through the 100 105 110 115 120 125

outer right-hand alternate contacts of relays 16 and 14. Relay 18 in operating completes a ground connection for the individual signal-control conductor A20, which 5 extends from the outer left-hand alternate contacts of relays 16 and 14, the left-hand normal contacts of relays 15 and 17 in series, the right-hand alternate contact of relay 18 to the conductor A20. Relay 19, 10 in operating, prepares a circuit for the control of the supervisory signal from the sleeve conductor of the cord circuit. The grounding of the start conductor X causes the operation of relay 330 to thereby cause 15 the operation of motor magnet MM controlling the selector switch SS. As in the previous cases, the selector switch SS is advanced step by step until the arm *a* encounters the contact corresponding to the ground- 20 ed signal control conductor A20, which is the first of the two contacts assigned to the jack 20 of the trunk line L1. When this contact is engaged, relay 332 operates over a circuit including its left-hand winding 25 and such conductor thereby opening the circuit of the motor magnet of the selector switch SS and stopping its further movement. The closure of the outer right-hand alternate contact of relay 332 completes a 30 circuit for the release magnet SRM of the sending distributor S which thereby releases the arm 319 of such distributor, and the arm, in making its complete revolution, engages the several sending segments of the distributor impressing certain impulses of current upon the common sending path P extending from station U to station V, as in the previously described cases. However, the combination of impulses differs 35 from that transmitted over such conductor upon the insertion of plug 1 into the jack 10 in that the impulse transmitted by the segment 303 is of positive polarity, while that transmitted by the segment 304 is of 40 negative polarity. As in the previously described cases, the completion of the cycle of the brush 319 causes certain apparatus to function to operate the selecting apparatus at the office U. The transmitted impulses are received at office V in a manner 45 similar to that previously mentioned, causing the operation thereof of the differentially polarized relay 335' and the receiving distributor R'RM. However, in this instance, due to the change in the polarities of the currents impressed upon the conductor by the segments 303 and 304 of the sending distributor S, relay 373' will not be operated, but relay 374' will be operated instead. In operating, relay 374' is locked 50 due to the prior operation of relay 367' and relay 380' will be operated and maintained in operated condition by relay 374'. Therefore, when the brush 356' of the receiving distributor R'RM engages the segments 350' and 351', current will be supplied through a circuit established from battery 377', through the lower normal contact of relay 376', the segment 350', the arm 356', the segment 351', the lower normal contact of relay 375', the lower alternate contact of relay 380', the upper normal contact of relay 381', the upper normal contact of relay 384', the upper normal contact of relay 390', the receiving conductor E'20 and the left-hand winding of relay 175 and winding of relay 176, in parallel, to ground. The operation of relay 176 has no effect at this time. Upon the completion of the sending of this signal, the signal-receiving and sending apparatus at both stations will be restored to normal. Relay 175 in operating, locks over an obvious circuit including its right-hand winding. The closure of the left-hand contact of relay 175 completes a 65 circuit for the motor magnet MM100, which extends from battery through the contact and winding of the motor magnet MM100, the normal contacts of relays 177 and 174, and the left-hand alternate contact of relay 175 to ground. The selector switch LS100 thereupon advances step by step until the brush arm *fn* engages a grounded contact indicating an idle line. A portion of 70 the conductors associated with the bank controlled by the brush *fn* lead to office W, while others lead to office Y; those to office W being connected to ground through apparatus at the office W, while those leading to office Y are connected to battery at the office Y. Upon engaging the contact of an idle trunk leading from office V to office W, relay 177 is operated over a circuit extending from battery through the left-hand winding of relay 177, the outer right-hand alternate contact of relay 175, the normal contact of relay 178, the brush arm *fn* and the contact of the bank in engagement therewith, the conductor F and the right-hand contact of relay 125 to ground. The opening of the normal contact of relay 177 opens the circuit of and discontinues the operation of motor magnet MM100, while the closure of the inner right-hand alternate contact of relay 177 locks such relay under the control of the inner right-hand alternate contact of relay 175. The closure of the outer right-hand alternate contact of relay 177 causes the operation of relays 154 and 157 over a circuit extending from battery through the outer right-hand alternate contact of relay 177, and the windings of relays 157 and 154 in series, to ground. Relay 154, in operating, disconnects the talking conductors extending to the plug 151 and connects the talking conductors of the trunk circuit through the amplifying repeater set RA to the engaged contacts of 75 80 85 90 95 100 105 110 115 120 125

the banks *j* and *k* of the line switch LS100. The closure of the outer left-hand alternate contact of relay 157 completes the filament circuit of the repeater used in the amplifying set RA, thereby rendering such repeater active. The connection of the brush arms *l* and *m* with the engaged contacts also connects the network 29' with the repeater set RA. Relays 124 and 125 operate over a circuit extending from battery through the outer right-hand alternate contact of relay 177, the brush arm *g* and the contact in engagement therewith, the conductor G and the windings of relays 124 and 125 in series to ground. Relay 125, in operating, removes the ground from the conductor F, thereby rendering the trunk line L1 busy to other connections and also to cause the operation of the usual busy signal 4' over an obvious circuit. Energization of relay 125 also opens the original energizing circuit for relay 177 but this relay remains operated due to the locking circuit established therefor. Relay 112 also operates due to the closure 25 of the left-hand alternate contact of relay 124, thereby disconnecting the jack terminals 110, 120 and 130 from operative association with the line circuit L1 extending from the office V to the office W. The closure of the inner right-hand alternate contact of relay 124 causes the operation of relay 114 over a circuit extending from battery through the inner right-hand alternate contact of relay 124, the winding of 30 relay 114, and the normal contact of relay 116 to ground. Relay 114 thereupon locks over an obvious circuit and causes the operation of relay 116 over a circuit extending from battery through the left-hand winding of relay 116 and the inner right-hand alternate contact of relay 114 to ground. The operation of relay 124 also establishes an energizing circuit for relay 132 extending from battery through the inner right-hand alternate contact of relay 124, the winding of relay 132 and the normal contact of relay 126 to ground. Conductor X'' is now grounded over a circuit, through the outer right-hand alternate contact of 35 relay 116, the outer right-hand alternate contact of relay 114, and the right-hand normal contacts of relays 115 and 117. The signal-control conductor A110 is also grounded over a path extending from ground through the outer left-hand alternate contacts of relays 116 and 114, the left-hand normal contacts of relays 115 and 117 in series, the right-hand normal contacts of relays 118 and 122 in series, to the conductor A110. The grounding of the start conductor X'' operates the start relay 330 of the transmitting set at the office V, which is similar in all respects to that previously described in connection with office U. Relay 330 in operating as before mentioned,

causes the operation of the selector switch SS and the associated sending distributor S to transmit over a common signaling path P extending from the office V to the office W, a combination of impulses for the purpose of selecting the proper signal-receiving apparatus at the latter office and for properly operating such apparatus. This is accomplished in the same manner as described in connection with the insertion of the plug 1 into the jack 10 of the line L1, extending from the office U to the office V, and upon the receipt of the same combination of impulses at the office W by receiving apparatus identical with that described in connection with the office V, the receiving lead E'110 at office W is selected and an impulse of current sent thereover which causes the operation of relay 271 due to current flowing through its left-hand winding. Relay 271, in operating, completes an obvious locking circuit therefor and causes the illumination of lamp 280 over a circuit, extending from battery through the right-hand alternate contact of relay 271, the right-hand normal contact of relay 256 and the lamp 280 to ground. As in the former cases, the receiving and sending apparatus at the office V and W are restored to normal upon the transmission of the final impulse. The closure of the left-hand alternate contact of relay 271 bridges the winding of supervisory relay 258 across the talking conductors of the trunk line L1 leading from the office V to the office W, the bridge for such winding including the right-hand normal contact of relay 257 and the left-hand alternate contact of relay 271.

Operator at office W connects the toll switching trunk with the line circuit T.

Upon being apprised that the line circuit T is desired by the calling subscriber, the operator at office W requests a trunk assignment from the toll switching trunk operator thereat. Having assigned the trunk Q to be used for this purpose, the toll switching trunk operator immediately inserts the plug 89 of the toll switching trunk Q into the jack 90 of the line circuit T, after having found such line to be idle. Relays 88 and 91 thereupon operate over a circuit extending from battery through the winding of relay 88, the sleeve contacts of plug 89 and jack 90 and the winding of cut-off relay 91 to ground. Relay 91 performs its usual function as a cut-off relay and disconnects the windings of the line relay 2 from the line conductors, thereby preventing the false illumination of the line signal 93. Relay 88, in operating, completes the continuity of the tip conductor which had heretofore been opened and associated with the operator's trunk set for use in making the usual busy test. The closure of the left-hand al-

ternate contact of relay 88 also causes the illumination of the lamp 87 at the toll switching trunk station over a circuit extending from battery through the lamp 87, the left-hand alternate contact of relay 88, resistance 94 and the normal contact of relay 86 to ground.

The operator at the terminating position of office W connects the toll line L1 with the toll switching trunk Q.

The operator at office W, before whom the line L1 terminates, upon observing the guard signal displayed by the lamp 280, and receiving the assignment of the trunk Q for use in completing the connection, inserts the plug 251 into the jack 80. Relay 252 thereupon operates over a circuit extending from battery through the winding of relay 252 and the sleeve contacts of plug 251 and jack 80 to ground. Relay 252, in operating, completes an obvious operating circuit for relay 256. The opening of the left-hand normal contact of the latter relay disconnects the operator's telephone testing equipment from the tip, and the closure of the left-hand alternate contact of such relay completes the continuity of the tip conductor of the trunk line L1. The opening of the right-hand normal contact of relay 256 opens the circuit of and extinguishes lamp 280 thereby notifying the operator at the terminating position of office W that the connection has been established. A circuit is also formed due to the closure of the tip conductor which extends from battery through the left-hand winding of relay 86, the left-hand normal contact of relay 84, the ring conductors of jack 80 and plug 251, the right-hand normal contact of relay 255, the right-hand normal contact of relay 254, the left-hand alternate contact of relay 271, the winding of supervisory relay 258, the right-hand normal contact of relay 257, the left-hand normal contacts of relays 254 and 255, in series, the left-hand alternate contact of relay 256, the tip contacts of plug 251 and jack 80, the right-hand normal contact of relay 84, and the right-hand winding of relay 86 to ground. Relays 86 and 258 operate in this circuit, the operation of relay 86 causing the extinguishment of lamp 87.

The energization of supervisory relay 258 causes the energization of relays 259, 260 and 261, the circuit for 259 being obvious. The circuit for relay 260 is traceable from battery through the relay 330', the conductors X' and X'', the inner right-hand contact of relay 265, winding and right-hand normal contact of relay 260, the left-hand contact of relay 261, the left-hand contact of relay 265, the outer left-hand contact of relay 269 and the alternate contact of relay 258 to ground. Relay 261 is energized over a circuit extending from grounded battery to

the winding and right-hand normal contact of said relay and from thence over the energizing circuit for relay 260. Relay 260, in operating, completes a locking circuit therefor, and relay 261 also completes a locking circuit which extends from battery through the winding and alternate contact of relay 261, the outer right-hand normal contact of relay 262, the outer left-hand normal contact of relay 269, and the alternate contact of relay 258 to ground. Relay 260, in closing its outer right-hand alternate contact, provides a ground connection for the signal-control conductor A'110, connected with the first of the two contacts on the level a' of the automatic selecting switch allotted to the trunk line L1, located at office W. The start magnet 330' of the sending equipment located at such office, is now energized in the operating circuit for relay 260 and completes the previously described operating circuit for the motor magnet MM' associated with the automatic selector switch SS'. The motor magnet which is of the self-interrupting type, well known in the art, advances the brushes of the switch step by step until the brush a' engages the contact of the associated bank to which the signal control conductor A'110 is connected, whereupon relay 332' operates over a circuit extending from battery through the right-hand winding of relay 332', the brush arm a' and the contact associated therewith, the signal control conductor A'110 and the right-hand alternate contact of relay 260 to ground. Relay 332', in operating, opens the circuit of the motor magnet MM' to stop the switch SS' in its advanced position. The sending distributor S' at the office W thereupon functions to successively connect with the common signaling path P extending from the office W to the office V, the impulses of current which are determined by the polarities connected with the individual sending segments of the distributor 301' and 306', as in the previously described cases of sending signals from the office V to the office U. The impulses are received at the office V by the differentially polarized relay 335 and the receiving distributor R located at office V for receiving the signals transmitted from the office W. As soon as the impulses are sent over the path P from the office W, the sending apparatus thereat restores to normal as in the previously mentioned instance. The receiving distributor R, located at office V, as before, selects the receiving conductor E'110 and transmits, as the operating impulse, an impulse of negative polarity which is received by the signal control relay 126. Relay 126 thereupon operates due to the current flowing in its left-hand winding, and completes a locking circuit for itself extending from battery through the inner right-hand alternate contact of relay 124, the

right-hand winding and right-hand alternate contact of relay 126 to ground. The closure of the left-hand armature of relay 126 completes a circuit, extending from battery through the right-hand alternate contact of relay 157, the winding of supervisory relay 158 at the office V, the left-hand normal contact of relay 171, the brush arm *i* and the engaged conductor *I*, the outer 10 right-hand alternate contact of relay 124, the left-hand alternate contact of relay 126, and the left-hand normal contact of relay 133, to ground. As in the previous instances, the receiving equipment associated with the 15 receiving distributor *R* at office V, restores to its normal condition in which it is disassociated from the trunk line *L1* as in the previous-mentioned cases of signaling between the offices V and U. The operation 20 of relay 158 causes the operation of relays 159, 160 and 161, as in the cases of calls terminating at office V, and the sending equipment is brought into service to transmit the selecting and operating impulses over the 25 common path *P*, extending from the office V to the office U in exactly the same manner as in the cases where the connection extended simply from the office U to the office V. However, the receiving conductor *E10* is selected and the last impulse of current flowing from the receiving distributor passes through the left-hand winding of receiving relay 26, causing its operation. Relay 26 30 closes a locking circuit for itself extending from battery through the left-hand alternate contact of relay 21, the right-hand winding and right-hand alternate contact of relay 26 to ground. The closure of the left-hand alternate contact of relay 26 places the resistance 35 in shunt relation 35 with the winding of relay 21, the shunt path being traceable from ground through the left-hand normal contact of relay 33, left-hand alternate contact of relay 26, the outer 40 right-hand normal contact of relay 24, the resistance 35, the left-hand normal contact of relay 23, the left-hand alternate contact of relay 19, through the sleeve of jack 20 where it joins the circuit previously traced 45 for relay 21. The resistance of the circuit in series with the winding of marginal relay 6 is thereby reduced to such a degree that relay 6 operates, causing the illumination of supervisory lamp 7 over an obvious circuit. 50

Operator at office U actuates the ringing key.

The operator at office U, upon observing the lighted condition of the supervisory lamp 60 7 associated with the jack 20, actuates the ringing key of the cord circuit *O*, causing ringing or other signaling current to flow over this circuit traceable from the source through the lower alternate contact of key 65 2, the ring contacts of plug 1 and jack 20,

the right-hand normal contact of relay 12, the winding of relay 13, the left-hand normal contact of relay 12, the tip contacts of jack 20 and plug 1, and the upper alternate contact of key 2, to ground. Relay 13 is 70 operated thereby to cause the operation of relay 15 over an obvious circuit. Relay 17 is thereupon deenergized by the opening of its locking circuit and the conductor *X* is disconnected from ground by the operation 75 of relay 15.

The operator at office U releases the ringing key.

Upon the restoration of the ringing key 80 2 of the cord circuit *O* to its normal position, relay 13 releases, causing the deenergization of relay 15, which in deenergizing, connects a ground to the start conductor *X*, over a circuit extending from ground through the outer right-hand alternate contacts of relays 16 and 14, the right-hand contact of relay 15 and outer right-hand contact of relay 17. A ground is also connected to the start conductor *A20*, which 85 may be traced from ground through the outer left-hand alternate contacts of relays 16 and 14, the left-hand contacts of relays 15 and 17, and the right-hand alternate contact of relay 18 to the signal-control conductor *A20*. The connection of the ground to the start conductor *X*, as in the previous case, operates start relay 330 to start the operation of motor magnet *MM*. The brush arms of the selector switch *SS* are thereby 90 advanced step by step until the arm *a* encounters the contact to which the individual signal-control conductor *A20* is connected. Thereupon relay 332 operates to cause the selector switch *SS* to be maintained in its 95 advanced position. Thereafter the signal-sending apparatus, including the sending distributor *S* and the selector switch *SS* function to transmit over the common signaling path *P* leading to the office V, a 100 series of impulses which are received by the differentially polarized relay 335' and the receiving distributor *R'* located at the latter office to select the receiving conductor *E'20* at such office and to transmit there- 105 over a signaling impulse. The character of the impulses is such that it has no effect upon the signal-receiving relay 175 but relay 176 is operated. With the relay 177 locked over a circuit including its right-hand winding and its inner right-hand contact, and the inner right-hand alternate contact of relay 175 as previously described, a circuit is formed extending from battery 110 through the winding of relay 115, the conductor *H* of the trunk circuit *L1*, the brush arm *h* in engagement therewith, the contact of relay 176 and the inner left-hand alternate contact of relay 177 to ground. Relay 176 then releases following the termination 115

of the impulse over conductor E'20. Relay 115 performs the same operation as described in connection with the ringing impulse and upon its release, causes the 5 grounding of the individual signal-control conductor A110 and the start conductor X'', of Fig. 3 and the conductors A10 and X of Fig. 5. The grounding of these two conductors causes the signal- 10 sending apparatus, comprising the sending distributor and the selector switch to function in exactly the same manner as described previously to transmit a series of 15 current impulses over the common signaling path connecting the offices V and W. These impulses are received at office W by the differentially polarized relay similar to relay 335' and the associated receiving distributor R' thereat and cause the selection 20 of and the transmission over the conductors E'10 E'110 of an impulse which is received by the signal-control relay 271. This impulse has no effect upon relay 271 since this 25 relay has been previously locked. Relay 270 is also operated at this time. Therefore, the impulse now transmitted operates relay 273 which locks under the control of relay 270. A circuit is now established for relay 267, similar to that described for relay 30 167. Relay 267, in operating, closes a circuit for the ringing relay 255, extending from battery through the winding of relay 255 and the left-hand contact of relay 267 to ground. Relay 267 also effects the 35 operation of relay 268. As in the previous instances, the receiving and sending apparatus is disconnected from the trunk circuit and immediately upon receiving the impulses, is rendered available for use by other 40 trunk circuits. Relay 255, in operating, closes a circuit, extending from the source of alternating current through the right-hand alternate contact of relay 255, the ring contacts of plug 251 and jack 80, the winding of relay 81, condenser 82, the tip contacts of jack 80 and plug 251, the left-hand alternate contact of relay 256 and the left-hand alternate contact of relay 255 to ground. The operation of relay 81 over 45 50 this circuit initiates the application of ringing current to the line circuit T as previously described.

As soon as slow release relay 270 has 55 fully restored to normal, relay 273 is released due to the opening of the circuit therefor, whereupon slow release relays 267 and 268 release and upon the complete release of relay 267, ringing relay 255 releases to remove the ringing current from 60 the toll line circuit L1 and the connected toll switching circuit Q. Upon the cessation of the ringing current, relay 81 releases to restore the apparatus of the toll switching trunk circuit in the same manner 65 as previously described to the condition in

which it was prior to the sending of the ringing signal from the station U. The apparatus associated with the trunk line L1 is also restored to the same condition as at the time above mentioned, so that each 70 time the ringing key of the cord circuit O at the station U is actuated and released; the same series of operations occur and, as a consequence, the signaling bell at the station on the line circuit T terminating at 75 office W is actuated for a pre-determined interval.

Subscriber at the station on the telephone line circuit T terminating at office W removes the receiver from the switchhook. 80

The subscriber at the station on the telephone line circuit T in responding to the operation of the ringer or signaling bell, removes the receiver from the switchhook 85 thereby causing the operation of supervisory relay 83 and consequent energization of relay 84 as heretofore described. Relay 84 in operating also causes the deenergization of the supervisory relay 258 in the trunk line circuit L1. Supervisory relay 258 in opening its alternate contact opens the energizing circuit of slow release relay 259 and opens the locking circuit of relay 261. Relay 259 is slow in releasing so that before it completely releases its armature, relay 263 is operated over a circuit extending from battery, through the winding of relay 263, the alternate contact of relay 258, and the normal contact of relay 259, to ground. However, the operation of relay 263 at this time 95 performs no useful function.

Upon the closure of the normal contact of relay 259, relay 269 operates over a circuit 100 extending from battery, through the winding of start relay 330' of the sending apparatus for sending impulses of current over the path P from station W to station V. This circuit extends further through the starting conductor X''', the outer right-hand normal contact of relay 265, winding of relay 269, the left-hand normal contact of relay 260, the right-hand alternate contact of relay 264 which has been previously energized due to the release of relay 260, the left-hand normal contact of relay 259, and the normal contact of relay 258, to ground. Relay 105 110 115 120 125 130 269 in operating locks through its left-hand alternate contact. The closure of the right-hand alternate contact of relay 269 connects ground to the signal control conductor C'110, which is connected to the second of the two contacts allotted to the jack 20 of the trunk line L1 of the selector switch SS'. The energization of the start relay 330' causes the operation of motor magnet MM' of the selector switch SS' to advance the various brushes of the switch step by step until the brush a' engages the contact connected with the signal control conductor C110. Relay

332' is thereupon operated over an obvious circuit and locks in the manner previously described to stop the motor magnet MM'. The brushes of the selector switch SS' thereupon connect certain polarities of current to the various segments of the sending distributor S' and such distributor is caused to complete a revolution to transmit the selected impulses over the common signaling path P to the office V where such impulses are received by the differentially polarized relay 335 and are distributed by the receiving distributor R. During the operation of the distributor, relay 265 operates over the circuit previously described therefor, following which the relay 269 is deenergized.

The receiving conductor E10 is selected by the action of the distributor as in the previously described manner. However, the last impulse which is transmitted over the selected signal receiving conductor is of a different polarity from that previously transmitted. This current when received by the signal receiving relay 126 at office V over the conductor E'110 is of such a polarity as will differentialize and thus cause the release of the locked relay 126. The relation of the number of turns of the two windings of the signal receiving relay 126 is such that when the positive polarity traverses the left-hand or energizing winding at the same time as current of a similar polarity traverses the right-hand winding, the relay is differentialized and releases its armatures. This opens the circuit extending from battery, through the right-hand alternate contact of relay 157, the winding of relay 158, the left-hand normal contact of relay 171, the brush arm *i* of the line switch LS100, the contact thereof connected with the conductor I, the right-hand alternate contact of relay 124, the left-hand alternate contact of relay 126, and the left-hand normal contact of relay 133, to ground. As in the previous instances, the sending and receiving apparatus located at the offices W and V is immediately disconnected from the trunk line L1 upon the transmission and receipt of the impulses and is rendered available for use with some other trunk of the group.

Relay 158 in releasing its armature opens the energizing circuit of slow release relay 159 and the locking circuit of relay 161. The apparatus connected with the trunk line L1 thereupon operates in the same manner as previously described in connection with the case of the called party at the station on the telephone line T terminating at the office V. This apparatus causes the common sending apparatus to be associated with the trunk line and to transmit from the common signaling path P to the office U the same set of impulses as previously mentioned in this connection. These impulses upon their re-

ceipt at the office U cause the selection of the release conductor E10 and cause the operation of the various apparatus associated with the trunk line L1 in the manner previously described for removing the resistance 35 70 from its parallel relation with the relay 21. Insufficient current now flows through the circuit including the marginal relay 6 to maintain it in an operative condition and it therefore releases to extinguish the lamp 7. 75 The conversation may then proceed over the inter-connected trunk line circuits L1 leading from offices U to V and from V to W.

Subscriber at the station on the line circuit T terminating at the office W restores the receiver to the switchhook.

At the conclusion of the conversation the subscriber on the telephone line circuit T terminating at office W restores the receiver to the switchhook thereby releasing supervisory relay 83 of the switching trunk Q at office W and consequently opening the circuit of relay 84. Relay 86 is again connected to the circuit across which the winding of relay 258 is bridged, thereby causing the operation of the latter relay. The energization of relay 258 causes the operation of relays 259, 260 and 261 in the manner described in connection with the completion of the connection through to the line circuit T.

The automatic selector switch SS' is thereupon operated in the same manner as before until its brush *a'* engages the grounded signal control conductor A'10 and the sending distributor S' thereupon transmits over the conductor the same combination of impulses as was transmitted when the plug 251 was inserted in the jack 80 of the toll switching trunk Q. The operation of relay 260 105 also causes the operation of relay 266. Relay 265 operates when relay 333' is energized and causes the release of relay 260. Thereupon relay 264 operates.

When the sending distributor S' at the office W restores to normal the automatic selector switch SS' and the sending distributor S' are removed from the operative association with the trunk line L1 and are available for use with other trunk lines or terminals thereof. The above mentioned transmitted impulses are received at the office V in the same manner as described in connection with the signal transmitted in response to the insertion of the plug 251 into the jack 80 and the last impulse being of the proper polarity to again operate relay 126, a circuit is completed from battery, through the right-hand alternate contact of relay 157, the winding of relay 158, the left-hand normal contact of relay 171, the brush arm *i* of the line switch LS100, the conductor I connected therewith, the outer right-hand alternate contact of relay 124, the left-hand alternate contact of relay 126, and the

normal contact of relay 133, to ground. Relay 158 operating over this circuit causes the same series of operations as previously described in connection with the insertion of the plug 251 into the jack 80 of the toll switching trunk Q and these operations include the sending of a similar combination of impulses over the common signaling path P from the office V to the office U where they are received in the manner previously described, and due to the character of the last impulse of the series, relay 26 is operated and locked. Resistance 35 is thereupon placed in parallel relation with the winding 15 of relay 21 to supply sufficient current to marginal relay 6 to cause its operation and the subsequent lighting of the lamp 7 serves as a disconnect signal to the operator at office U.

20 *Operator at office U disconnects the toll cord circuit O from the jack 20 of the trunk line L1.*

The operator at office U upon observing 25 the lighted condition of the supervisory lamp 7 withdraws plug 1 from jack 20 causing the release of relays 21, 6, 25 and 14. The release of relay 6 opens the circuit of and extinguishes the supervisory lamp 7. The 30 release of relay 14 causes the grounding of conductor C20 and starting conductor X. As in the various cases, the starting conductor X being grounded causes the operation of the selector switch SS to advance the 35 brush arms step by step. In this case, however, the second contact associated with the brush arm a is grounded while the first contact is not. Therefore, when the brush arm a reaches the second contact associated with 40 the jack 20, relay 332 operates and the sending distributor S thereupon functions in the manner previously described to transmit a combination of impulses over the common signaling path P to the office V where it is 45 received by the differentially polarized relay 335' and the associated receiving distributor R', and the impulses are caused to select the receiving conductor E'20 leading to the trunk which is being employed. However, 50 the character of the impulse last transmitted in the series is such that it differentiates and causes the release of relay 175 in the manner mentioned in connection with the other signal receiving relays. The release of relay 175 also causes the release of 55 relay 177. The opening of the inner left-hand alternate contact of relay 177 permanently removes the ground from the brush arm h which is connected thereto through 60 the contacts of slow release relay 176. The opening of the right-hand alternate contact of relay 177 also causes the release of relay 154 which then reestablishes the continuity 65 of the trunk conductors leading from jacks 10, 20 and 30 to office V. Relay 157 in re-

leasing also renders the amplifier RA ineffective and disconnects the battery connection with the supervisory relay 158 thereby restoring the latter relay to its normal association with the trunk line conductors leading 70 to the plug 151. The removal of battery by the opening of the outer right-hand alternate contact of relay 177 from the brush arm g causes the release of relays 124 125 and 112. In releasing, the latter relay disconnects the 75 talking conductors J and K from the trunk line extending to office W. The relay 125 in releasing, renders the busy signal at the office V ineffective as well as restores the selected trunk line circuit L1 from the office 80 V to the office W to an idle condition so that it may be reselected. The brushes of the line switch LS100 remain in their actuated positions until again operated to select an idle trunk. The release of relay 124 disconnects battery from the winding of relay 114 to cause its release. Signal control conductor C110 is thereupon grounded simultaneously with the grounding of the start conductor X'' in a manner similar to that described 85 in connection with the apparatus at office U and the grounding of these conductors cause the sending of a series of impulses from office V to office W in the same manner as previously described. These impulses are received at the office W and translated to apply to the receiving conductor E'110, an impulse of the character which will cause the differentiation and release of relay 271. The removal of battery from the right-hand alternate contact of relay 271 releases 90 relays 266 and 264, while the closure of the right-hand normal contact of relay 271 lights the lamp 280 over a circuit extending from battery, through the normal contact of relay 271, the right-hand alternate contact of relay 256, and the lamp 280 to ground. The lighting of the lamp 280 serves as a disconnect signal to the operator at office V. The release of relay 271 also 95 opens the circuit including the supervisory relay 258 of the trunk line L1 and the relay 86 of the toll switching trunk Q, causing the release of both of the latter relays. The opening of the alternate contact of supervisory relay 258 restores relays 259 and 261 to normal. Relay 263 is energized after the release of relay 258 and before the release of relay 259 but is deenergized when slow release relay 259 is completely deenergized. 100 The energization of relay 263 at this time does not perform any useful function. The release of the relay 86 of the trunk circuit Q causes the lighting of the lamp 87 over a circuit similar to that previously traced 105 to serve as a disconnect signal for the toll switching operator at whose position the trunk circuit Q terminates. The terminating operator and the toll switching trunk 110 operator at office W may upon observing the 115

120
125
130

lighted condition of the respective supervisory lamps 280 and 87 withdraw the plugs 251 and 89 from the jacks 80 and 90 respectively, thereby restoring all apparatus 5 associated with the toll switching trunk Q and the line circuit 90 to its normal condition. All the other apparatus associated with the signaling and talking conductors of the trunk line L1 has been previously restored to normal so that the trunk is available for further selection and the impulse transmitting mechanism is available for use with any other trunk.

15 *Subscriber at the station on the telephone line T terminating at office W recalls the operator at office U.*

Should the subscriber at the station on the telephone line circuit T terminating at office 20 W after answering the call, in case the connection is established between the toll cord circuit O at the office U and such telephone line by means of the jack 20 of the trunk line L1 extending between the offices U, V and W, 25 as well as the toll switching trunk Q, decide to recall or to signal the operator at office U, this result may be accomplished by repeatedly opening and closing the switchhook contact at the station on such line. 30 From the previous description it is evident that while the receiver at the station on the line circuit T is removed from the switchhook, the supervisory relay 258 and all relays 259 to 265 and 269, controlled by such 35 supervisory relay at the office W are de-energized. All other relays associated with the incoming end of the trunk line L1 at the office W, the signal receiving relay 271 and the relay 256 are energized and the 40 signal receiving relay 273, the ringing relay 255 and the slow releasing relays 270, 267 and 268 are deenergized. Relay 259 is made slow in releasing so that its alternate contact will be maintained closed during the short 45 periods when the alternate contact of the supervisory relay 258 is opened in response to the repeated opening and closing of the switchhook contact at the station on the line circuit T when the subscriber thereat is 50 signaling the operator at the office U. Similarly, relay 263 is made slow in releasing so that its contact is maintained opened during a short period when the normal contact of the supervisory relay 258 is opened 55 in response to such actuation of the switchhook. Relays 262, 266 and 264 are also made slow in releasing to assist in the control of the recall signal when the subscriber at the station is recalling the operator at office U. 60 Upon the first opening of the switchhook contact, the supervisory relay 258 is energized, thereby energizing relays 259, 260, 261 and 266, as previously described in connection with the answer of the called party. 65 In response to the operation of these relays

the automatic selector switch SS' at the office W advances the brushes of such switch until the contact to which the individual signal control conductors A'110 and A'10 temporarily grounded by this series of operations is connected to the arm a', when relay 332' operates. The operation of relay 332' energizes the release magnet SRM' of the sending equipment at the office W whereupon the associated sending distributor 70 transmits over the common conductor P a combination of impulses determined by the polarities connected with the individual sending segments thereof as determined by the position of the brushes of the switch 80 SS'. During the transmission of the series of impulses, relay 265 operates as before described and relay 264 energizes and locks. The receiving distributor R at office V functions upon the reception of these transmitted impulses by the relay 335 to cause the temporary energization of relay 367 as well as the energization of certain of the pyramid relays whereby the proper receiving lead E'110, is selected and an impulse is 90 transmitted thereover to cause the energization and locking of signal receiving relay 126 at the office V. As previously described in connection with the answer of the called party whose line terminated at the 95 office W, the operation of relay 126 completes a circuit which includes the supervisory relay 158 and causes its operation. The operation of relay 158 then causes similar operations of relays located at the office 100 V and associated with the trunk line L1 similar to that described in connection with the answer of the called party whose line terminated at office V. Following the operations of these relays, the transmitting apparatus at the office V transmits over the common signaling path P to the office U a combination of impulses which upon being received at the office U to select the proper receiving lead E transmits thereover an impulse of current to cause the operation and locking of relay 26 thereat which, as before described, places the resistance 35 in parallel relation with the winding of relay 21 to cause the operation of marginal relay 6 115 thereby causing the illumination of supervisory lamp 7 of the cord circuit O at the office U as in the case of a disconnect signal.

The closure of the switchhook contact at the station on the telephone line circuit T terminating at office W shortly after the above mentioned opening thereof causes the deenergization of supervisory relay 258. Relay 261 immediately releases and relay 263 is operated. The subsequent energization of the supervisory relay 258 in response to the next opening of the switchhook causes relays 260 and 261 to operate in the order named as previously described. When relay 260 operates, relay 262 is operated over 120 125 130

a circuit extending from battery, through the right-hand alternate contact of the signal receiving relay 271, the left-hand normal contact of relay 257, the winding of relay 262, the inner right-hand normal contact thereof, the left-hand alternate contact of relay 264, and the inner left-hand contact of relay 260, to ground. Relay 262 immediately locks through its inner right-hand alternate contact and the inner left-hand normal contact of relay 269, to ground. Upon the energization of relay 262, relay 261, which is already energized, is locked in the same manner as described in connection with relay 161 whereby relay 261 is removed from the control of the supervisory relay 258 during the rapid operation thereof in response to the actuation of the switchhook. The energization of relay 260 causes the automatic selector switch SS' to operate and starts the sending distributor S' at the office W to transmit over the common signaling path P a combination of impulses corresponding to those originated by the insertion of the plug 1 into the jack 10 of the trunk line L1, as determined by the selector switch SS'. These impulses upon being received by the common receiving apparatus at the office V causes the temporary energization of certain relays thereat as before and after the proper signal receiving conductor E'110 is selected, an impulse of current is sent thereover which operates signal receiving relay 133 over a circuit from battery, the segments 350 and 351 in cooperation with brush arm 356 of the receiving distributor R, the lower normal contacts of relays 375 and 380, the lower alternate contact of relay 381, the upper normal contacts of relays 383 and 388, signal receiving conductors E10 and E'110 the normal contact of relay 132, and the left-hand winding of relay 133, to ground. This current also flows through the left-hand winding of relay 126, but due to the similarity of the polarity thereof with that of the current flowing through the locking winding of such relay it has no material effect on relay 126. Relay 133 in operating locks through its right-hand contact and the inner right-hand alternate contact of relay 124. The closure of the left-hand alternate contact of relay 133 connects the interrupter 134 in series with the left-hand contact of relay 126, the outer right-hand alternate contact of relay 124, the conductor I, the brush arm i of the line switch LS100, the left-hand normal contact of relay 171, the winding of supervisory relay 158, and the right-hand alternate contact of relay 157 to battery.

The repeated operation and release of supervisory relay 158 in response to this intermittent circuit causes the relays associated with and controlled by such relays to function in a manner similar to that caused by

the rapid opening and closing of the switchhook at the station on the line circuit T terminating at office V as previously described.

In response to such operation the sending equipment located at the office V transmits a combination of impulses over the common signaling path P to the office U where they are received, the first impulse thereof flowing over the selected receiving conductor E10 and through the left-hand winding of signal receiving relay 33. Relay 33 thereupon operates and due to the fact that the polarity of the current impulse is the same as that flowing through the left-hand winding of relay 26, such relay which is in an operated condition is unaffected by such impulse. The polarity of the current flowing through the left-hand winding of relay 33 is the same as that which flows through the locking circuit for such relay completed upon its operation so that relay 33 is maintained in an operated condition. The closure of the left-hand alternate contact of relay 33 connects interrupter 34 in series with the left-hand alternate contact of relay 26 to the right-hand normal contact of relay 24 and the resistance 35 which is in parallel relation with the winding of relay 21. The intermittent current flowing through such circuit due to the interruptions caused by the interrupter 34 causes the intermittent operation and release of the marginal relay 6 to cause flashing of the lamp 7. No more signals are transmitted over the common signaling paths P extending from the office W to the office V and from the office V to the office U after the second opening of the switchhook contact at the station on the line circuit T, terminating at the office W. The flashing of the lamp 7 continues at a constant rate which attracts the attention of the operator, but it is necessary to continue to open and close the switchhook contact at the distant station in order to maintain the signal in connection with interrupter 34.

If after repeatedly opening and closing the switchhook contact the subscriber should leave the switchhook contact closed then the supervisory relay 258 at office W is deenergized and after a comparatively extended deenergization of such relay, relay 259 releases and upon the closure of its normal contact relay 269 operates and the energization of relay 269 releases relays 261, 262, 266 and 264. The operation of relay 269 also grounds the signal control conductor C' 110 and the start magnet 330' is again energized. The common sending equipment at the office W again functions to transmit a series of current impulses over the common signaling path P to the office V where these impulses select the proper receiving conductor E and transmits a current impulse over such signal receiving conductor of the polarity adapted to differentialize and cause the release of re-

lay 126. The opening of the left-hand alternate contact of relay 126 permanently opens the circuit previously traced for the supervisory relay 158 which releases and 5 causes the various associated relays to function as in the case previously described where the switchhook contact is opened at the station on the line circuit T terminating at office V. Thus the sending apparatus located at office V functions as in the previous instances to transmit a combination of impulses over the common signaling path P to the office U which selects the proper receiving conductor E thereat and transmits there- 10 over a current impulse of the proper polarity to deenergize relays 26 and 33 thereby interrupting the intermittent circuit formed through the resistance 35. Relay 6 is thereby released and lamp 7 is permanently extin- 15 guished. Relay 32 again energizes upon the release of relay 26.

If after repeatedly opening and closing the switchhook contact the subscriber should leave the switchhook contact opened, 20 the supervisory relay 258 would be energized. An extended energization of such relay causes the deenergization of relay 263 which causes the energization of relay 269 and grounding of the conductor C'110. 25 The selector switch SS' and the other sending apparatus at office W again function in the manner previously described to transmit the combination of impulses over the common signaling path P from the office 30 W to the office V which causes the selection of the receiving conductor E and the transmission of a current impulse thereover to release relays 126 and 133 so that the interrupter 134 is disconnected from the circuit 35 including relay 158 and said relay momentarily releases. Following the release of relay 269 due to the operation of relay 265, relay 260 is operated over the conductor X''' and the contacts of relays 265, 261, 269 40 and 258. Relay 261 also operates and locks as previously described. The operation of relay 260 connects ground to the individual control conductor A'110 which results in the transmission of a series of impulses 45 from office W to office V, whereupon relay 126 at the latter office is operated and locked. The operation of relay 126 again connects ground to the conductor I, whereupon the supervisory relay 158 is again operated. 50 Relay 158 upon remaining energized for a sufficient period during the permanent closure of this circuit causes the various associated relays to function as described in connection with the previous instances 55 and the common sending apparatus associated with the trunk line L1 at office V transmits a combination of impulses over the common signaling path P to the office U to again select the receiving conductor E 60 and to transmit thereover an impulse of cur-

rent. The polarity of this impulse effects the re-release of relays 26 and 33 to extinguish the lamp 7. After this impulse has been transmitted and relay 169 released, relay 160 operates as before described to ground the conductor A'10 which results in the energization of relay 26. The resistance 35 is thereby included in parallel with the winding of relay 21 in a circuit provided with a permanent ground at the 70 normal contact of relay 33. Marginal relay 6 thereupon receives sufficient current to cause its energization and to thereby cause the permanent illumination of the lamp 7, this latter lamp serving as a disconnect signal to the operator at the office U. 75

The operator at office U extends a call to a line circuit T terminating at office Y.

Assuming that the operator at office U 80 desires to extend a connection to a station on line circuit T terminating at office Y which must be reached through the office V and the toll switching trunk Q at office Y, the operator at office U inserts the plug 85 of cord circuit O into jack 30 of the line L1 which line has been found to be idle. Relays 31 and 25 thereupon operate over a circuit from battery, through the winding of marginal relay 6, the sleeve contacts of 90 plug 1 and jack 30, and the windings of relays 31 and 25, in series, to ground. The closure of the left-hand contact of relay 25 causes the display of a busy signal by the 95 operation of the signaling device 4 over an obvious circuit. Relay 6 being marginal does not operate over the circuit just traced therefor. Relay 31 in operating causes the 100 operation of relay 14 over a circuit extending from battery, through the left-hand alternate contact of relay 31, the winding of relay 14, and the normal contact of relay 16, to ground. Relay 14 locks as hereinbefore set forth. Relay 32 also operates over a circuit from battery, through the left-hand alternate contact of relay 31, the winding of relay 32, and the right-hand normal contact of relay 26, to ground. 105 The operation of relay 14 causes the operation of relay 6 as previously described. Relays 22 and 23 also operate over a circuit traced from battery, through the inner right-hand normal contact of relay 24, the right-hand normal contacts of relays 11 and 21 in series, the right-hand alternate contact of relay 31, the windings of relays 23 and 22 in series, and the inner right-hand alternate contact of relay 14, to ground. 110 Relay 23 thereupon locks over a circuit extending from battery, through the right-hand alternate contact and winding of relay 23, and from thence over the circuit just described. The closure of the outer right-hand alternate contact of 115 relay 16 completes a ground connection 120 125 130

- through the outer right-hand alternate contact of relay 14 and the right-hand normal contacts of relays 15 and 17 in series, to the starting conductor X. Relay 5 22 in operating completes a ground connection for the individual signal control conductor A30 which extends from ground at the outer left-hand alternate contacts of relays 16 and 14, the left-hand normal contacts of relays 15 and 17, the right-hand normal contact of relay 18, and the right-hand alternate contact of relay 22. Relay 23 in closing its left-hand alternate contact prepares a circuit for the control 10 of the marginal relay 6 over the sleeve conductors of the cord and line circuits. As in the previous instances, the grounding of the starting conductor X and the signal control conductor A30 cause the 15 common impulse sending apparatus at the office U to transmit a combination of impulses over the common signaling path P to the office V where such impulses are received and serve to select the receiving conductor E'30 and to transmit thereover an impulse, causing the operation of signal receiving relay 178 as well as slow release relay 179. Upon the receipt of the impulses all of the common sending and receiving apparatus is restored to normal. 20 Relay 178 in operating locks over an obvious circuit. The closure of the left-hand contact of such relay completes a circuit for motor magnet MM100 which extends 25 from battery, through the contact and winding of motor magnet MM100, the normal contacts of relays 177 and 174 in series, and the left-hand alternate contact of relay 178, to ground. The selector switch LS100 thereupon advances step by step until the brush arm *fn* engages a contact connected to battery indicating an idle line to the office Y. In the previous instances the indication of an idle line 30 to the office W was given by the use of a grounded contact on the bank of the line switch LS100, but in this instance the lines leading to the other office Y are adapted to provide a contact connected to battery in case they are idle. Therefore, 35 when such contact is engaged relay 174 operates over a circuit extending from battery, through the contact of relay 136 of the selected idle line circuit, the conductor N, the contact and associated brush arm *fn* of the switch LS100, the outer right-hand alternate contact of relay 178, and the left-hand winding of relay 174, to ground. The opening of the normal contact of 40 relay 174 discontinues the operation of motor magnet MM100 so that the various arms of the line switch LS100 remain in their attained position.
- The closure of the inner right-hand alternate contact of relay 174 locks such 45 relay under control of signal receiving relay 178. The closure of the outer right-hand alternate contact of relay 174 causes the operation of relays 157 and 154 over a circuit extending from battery, through 50 the outer right-hand alternate contact of relay 174 and the windings of relays 157 and 154 in series, to ground. These latter mentioned relays function in the same manner as described in connection with the extension of a call to a line circuit terminating at office W so that further description will be omitted.
- Relays 124 and 136 operate, the latter 55 relay replacing the relay 125 of the trunk circuit shown at office V. References hereinafter made to relays of the trunk circuit L1, are to be understood as referring to similar relays of the selected trunk circuit extending from office V to office Y. The 60 circuit for the operation of relays 124 and 136 may be traced from battery, through the outer right-hand alternate contact of relay 174, the brush arm *g*, the conductor G in connection therewith, and the windings of relays 124 and 136, to ground. Relay 136 in operating causes the operation 65 of a busy signaling device, as in the case of the operation of the relay 125 in the former instance. The opening of the right-hand contact of relay 136 also removes the battery connection from the associated contacts of the selector bank, thereby rendering the trunk line busy to provide 70 against the reselection of such trunk during the connection. Relay 112 operates in a manner similar to that described in connection with the extension of the call to the office W and the closure of the right-hand alternate contact of relay 124 causes 75 the operation of relay 114 as previously described. Relay 114 locks over an obvious circuit and causes the operation of relay 116. Conductor X'' is thereby grounded 80 in a manner similar to that described in connection with the extension of the call to the office W and the signal control conductor A110 is also grounded over a similar path so that the common impulse sending apparatus at the office V is 85 caused to transmit a combination of impulses over the common signaling path P extending from the office V to the office Y. Such impulses are received at the office Y and are caused to select the proper receiving conductor E'110 and to transmit thereover 90 current of the proper polarity to cause operation of a relay 271 at office Y. The operation of relay 271 causes the display 95 of the guard lamp which is illuminated by current flowing over a circuit from battery, through the right-hand alternate contact of relay 271, the right-hand normal contact of relay 256, and the winding of lamp 280, to ground.

It is assumed that the apparatus at office Y is the same as that at office W so that no separate drawings are shown therefore and no separate reference characters 5 will be mentioned in regard to the similar apparatus.

The operator at the terminating position at office Y communicates with the toll switching trunk operator at such office over 10 an ordinary call circuit or in some other usual manner and is assigned the toll switching trunk Q for use in extending the call to the station on the line circuit T.

15 *Operator at office Y connects the toll switching trunk with the line circuit T.*

Upon being apprised that the line circuit T desired by the calling subscriber is available through the toll switching trunk 20 Q, the toll switching trunk operator immediately inserts the plug 89 of the trunk Q into the jack 90 of the line circuit T after having caused such line to be idle. The operation in response to this connection is 25 the same as that described in the case of the extension of the call to the line circuit T terminating at office W and its description in detail will be omitted.

From this point on the operating features 30 are identical with those described in connection with the extension of the call to the telephone line T terminating at office W and it appears that the detailed description thereof is unnecessary to the proper understanding 35 of the invention. In each case the transmission of the supervisory and other signals from one office to the adjacent office is accomplished in the manner as previously described, it being necessary to 40 have separate combinations of impulses to represent the different signals of the various lines involved as well as to represent the character of the connection which is involved.

45 It will be evident from the arrangement shown at each office that each trunk line circuit is provided with three jacks or terminals and that each operator may extend calls onward in the same manner as described for the operator at office U. Thus at office V, calls may be initiated at jacks, 110, 120, and 130. The common signaling paths and the interconnecting trunk circuits may be of any number and the operator at 50 each station may establish a connection with the adjacent station or with an idle line leading to either of two distant stations which are available through an intermediate station.

55 60 What is claimed is:

1. In a signaling system, a plurality of offices, a trunk circuit interconnecting said offices, means responsive to the seizure of said trunk circuit for transmitting impulses 65 from one of said offices to a second office

for joining said offices, means at said second office thereupon operable to connect said second office with any one of a plurality of other offices over said trunk circuit, and means for then identifying said trunk circuit at said other office. 70

2. In a signaling system, a plurality of offices, a trunk circuit interconnecting said offices, means responsive to the seizure of said trunk circuit for transmitting impulses 75 from one of said offices to a second office for joining said offices, means at said second office thereupon operable to connect said second office with any one of a plurality of other offices over said trunk circuit, and repeater sets for said trunk circuit operated 80 by said impulses.

3. In a telephone system, an originating office, an intermediate office, a plurality of terminating offices, a plurality of trunk circuits interconnecting the originating and intermediate offices, a signaling path common thereto for joining the offices, a plurality of trunk circuits interconnecting each of the terminating offices with the intermediate office, a plurality of connecting terminals for each trunk at the originating office, a link circuit at the originating office for connection with the terminals, means responsive to the connection of the link circuit with one of the connecting terminals of a selected trunk circuit to transmit a code of current impulses over the common signaling path to the intermediate office, means at the intermediate office to receive the impulses, and means responsive thereto to automatically connect with the selected trunk from the originating office an idle one of the plurality of trunks extending to a selected one of the terminating offices as 90 determined by the connecting terminal associated with the link circuit. 100

4. In a telephone system, an originating office, an intermediate office, a plurality of terminating offices, a plurality of trunk circuits interconnecting the originating and intermediate offices, a signaling path common thereto for joining the offices, a plurality of trunk circuits interconnecting each of the terminating offices with the intermediate office, a plurality of connecting terminals for each trunk at the originating office, a link circuit at the originating office for connection with the terminals, means responsive to the connection of the link circuit with one of the connecting terminals of a selected trunk circuit to transmit a code of current impulses over the common signaling path to the intermediate office, means at the intermediate office to receive the impulses, means responsive thereto to automatically connect with the selected trunk from the originating office an idle one of the plurality of trunks extending to a selected one of the terminating office as 110 115 120 125 130

terminated by the connecting terminal associated with the link circuit, and a signaling device located at the terminating office responsive to such interconnection of the 5 trunk circuits.

5. In a signaling system, a plurality of offices, trunk circuits interconnecting said offices, impulse controlled means at one office responsive to the seizure of one of said 10 trunk circuits at a second office for selecting a trunk circuit extending from the first named office to any one of a plurality of other offices, and means at the latter office for identifying the selected trunk circuit.

15. 6. In a signaling system, a plurality of offices, a trunk circuit interconnecting said offices, means responsive to the seizure of said trunk circuit for transmitting impulses from one of said offices to a second office

20. for joining said offices, selective switches at said second office thereupon operable to connect said second office with any one of a plurality of other offices over said trunk circuit, and means for then identifying said 25 trunk circuit at said other office.

7. In a signaling system, a plurality of offices, trunk circuits interconnecting said offices, impulse controlled selective switches at one office responsive to the seizure of one 30 of said trunk circuits at a second office for selecting a trunk circuit extending from the first named office to any one of a plurality of other offices, and means at the latter office for identifying the selected trunk 35 circuit.

8. In a signaling system, a plurality of offices, a plurality of trunk circuits interconnecting said offices, a plurality of correspondingly arranged terminals for each 40 trunk circuit at said offices, means responsive to a connection to a terminal of one of said trunk circuits at one office to identify at another office a terminal thereat other than the one which corresponds to the first 45 named terminal, means responsive to the identification of said terminal for selecting a trunk circuit extending between said other office and any one of a plurality of other offices, and means at the last named office 50 for identifying the selected trunk circuit.

9. In a signaling system, a plurality of offices, a plurality of trunk circuits interconnecting said offices, a plurality of corre-

spondingly arranged terminals for each trunk circuit at said offices, means responsive 55 to a connection to a connecting terminal of one of said trunk circuits at one office to identify at another office a terminal thereat of said trunk circuit other than the one which corresponds to the first named terminal, means responsive to the identification 60 of said terminal for selecting a trunk circuit extending between said other office and any one of a plurality of other offices, and means at the last named office for identifying the selected trunk circuit. 65

10. In a signaling system, an office, a second office, a plurality of other offices having terminals at said second office, a plurality of trunk circuits interconnecting 70 all of said offices, a signaling path common to said trunk circuits, means responsive to impulses transmitted over said signaling path for establishing a connection between the first and second named offices over one 75 of said trunk circuits, and means for selecting one of said terminals at the second office to extend a connection over said trunk circuit to one of said plurality of other offices.

11. In a signaling system, an office, a second office, a plurality of other offices having terminals at said second office, a plurality of trunk circuits interconnecting 80 all of said offices, a signaling path common to said trunk circuits, means responsive to 85 impulses transmitted over said signaling path for establishing a connection between the first and second named offices over one of said trunk circuits, means for selecting one of said terminals at the second office, and 90 means then operable to select another trunk circuit to extend said connection from the second office to one of said plurality of other offices.

12. In a switching system, an office, a plurality of other offices, a plurality of trunk circuits interconnecting said offices, a path common to said trunk circuits and extending between said offices, and means controlled over said path for selecting a trunk 100 circuit extending between said office and any one of a plurality of said other offices.

In witness whereof, I hereunto subscribe my name this 17th day of December A. D., 1920.

WILLIAM L. DODGE.
